UNITED STATES PATENT OFFICE.

WILFRED I. OHMER AND JOHN E. McALLISTER, OF DAYTON, OHIO, ASSIGNORS TO THE RECORDING AND COMPUTING MACHINES COMPANY, OF DAYTON, OHIO, A CORPORATION OF OHIO.

COMPUTING AND RECORDING MACHINE.

1,169,860.

Specification of Letters Patent.

Patented Feb. 1, 1916.

Application filed September 16, 1910. Serial No. 582,371.

To all whom it may concern:

Be it known that we, WILFRED I. OHMER and JOHN E. McALLISTER, citizens of the United States, residing at Dayton, in the county of Montgomery and State of Ohio, have invented certain new and useful Improvements in Computing and Recording Machines, of which the following is a specification, reference being had therein to the accompanying drawings.

This invention relates to computing and recording machines, and more particularly to that type of machine commonly known as a taximeter.

The object of the invention is, primarily, to provide a machine which will compute, register and indicate the amount of the fare due for a given trip of a passenger vehicle, basing this computation upon both the distance traveled and the waiting time, the latter comprising the time during which the vehicle, while still in the employ of the passenger, is standing still or moving at a very low rate of speed; which will print and issue a ticket showing the amount of said fare; which will print and retain a record of the amount of said fare, the distance traveled and the time consumed by the trip, together with such other items as may be thought desirable, such as the number of pieces of baggage carried, etc.; which will compute and register the total of the several items for a predetermined period of time, such as a day; which will print a record of the several totals at the end of said predetermined period of time; which will thereby provide the cashier, or other authorized agent of the company operating the vehicle, with a printed detail record of each trip made by the vehicle during such period of time, including the distance traveled, the time consumed, the fare received and the baggage carried, each trip being identified by a trip number and each record being identified by the number of the driver who made the same; and which will also provide such agent with a record of the total amount of the fares received, the total number of pieces of baggage carried and the total number of trips made during the day and the total number of miles traveled by the vehicle.

It is also an object of the invention to provide a machine of this type in which the position of the flag, which indicates whether the vehicle is engaged or is for hire, will

control the operation of the registering mechanism, either in part or as a whole; and in which the operation of the flag itself will be controlled by the printing mechanism in such a manner as to make it necessary for the driver, first, to print a record showing the condition of the registering devices at the beginning of the trip, before he can move the flag into its "engaged" position, and, second, to print a record showing the condition of the registering devices at the end of the trip, before he can move the flag into its "empty" or "for hire" position.

It is also an object of the invention to provide a machine of this type in which the movement of the flag into its "engaged" position will cause the registering devices to register the amount of the minimum fare; and in which the minimum fare so registered will be accurately included in the total fare for the trip, if this total fare exceeds the amount of the minimum fare.

In the accompanying drawings, Figure 1 is a front elevation of a machine embodying the invention, with the outer casing removed; Fig. 2 is a rear elevation of such a machine; Fig. 3 is a top plan view of the same; Fig. 4 is a detail, plan view of the worm wheel shaft, intermediate shaft and the several parts carried thereby, showing the two shafts spaced apart an exaggerated distance; Fig. 5 is a transverse, sectional view, taken on the line $\alpha\alpha$ of Fig. 3 and looking in the direction of the arrows; Fig. 6 is an elevation of the right-hand end of the machine; Fig. 7 is a detail view of one of the cam plates for the printing mechanism; Fig. 8 is an elevation of the left-hand end of the machine; Fig. 9 is a detail view of the operating devices for the feeding rollers for the cashier's record; Fig. 10 is a front elevation of a portion of the right-hand end of the machine, showing the operating mechanism for the ticket feeding roller and also showing the visual indicator; Fig. 11 is a rear elevation of a portion of the right-hand end of the machine showing the printing handle, the several cams actuated thereby and their coöoperating devices; Fig. 12 is a detail view showing the driving connections for the visual indicator; Fig. 13 is a similar view showing the position of the connecting gear when the transfer shaft has been swung outward; Fig. 14 is a top, plan view of a por-

tion of the right-hand end of the machine showing the flag mechanism; Fig. 15 is an end elevation of a portion of the right-hand end of the machine showing the printing handle, the flag and the locking devices for the latter; Fig. 15^a is a detail view of the resetting device for the trip mileage cam. Fig. 16 is a detail view of the ticket cutting devices and the actuating cam therefor; Fig. 17 is a detail view of a portion of one of the cam plates for the printing mechanism showing the course of travel of the printing roller when printing the zero and trip records, respectively; Fig. 18 is a detail view of the flag and one of its locking devices, with the flag in its "engaged" position; Fig. 19 is a longitudinal, sectional view of one of the countershafts showing the resetting mechanism therefor; Fig. 20 is a transverse sectional view of the same; Figs. 21 and 22 are detail views of the two actuating cams for the resetting mechanism; Fig. 23 is a detail view of the slide bar forming a part of the resetting mechanism; Fig. 24 is an end elevation of the operating devices for the printing mechanism; Fig. 25 is a detail view of the pawl and ratchet wheel by means of which the printing cam is driven; Fig. 26 is a detail view of the locking arm for the flag and its releasing device; Fig. 27 is a transverse sectional view showing the registering mechanism for the trip mileage; Fig. 28 is a similar view showing the registering mechanism for the total mileage; Fig. 29 is a detail view of the flag-controlled mechanism for connecting the registering devices with their driving mechanism; Fig. 30 is a transverse, sectional view, taken on the line y y of Fig. 4 and looking in the direction of the arrows; Fig. 31 is a sectional view, taken on the line z z of Fig. 4 and looking in the direction of the arrows; Fig. 32 is a detail view of the push-bar for actuating the baggage registering devices; Fig. 33 is a top, plan view of the baggage registering devices; Fig. 34 is an end elevation of the same; Fig. 35 is a detail view of the worm and worm gear by means of which movement is transmitted from the wheel driven devices to the worm wheel shaft; Fig. 36 is a detail view of the clutch mechanism and one-tooth pawl forming a part of the resetting devices for the trip mileage cam; Fig. 37 is a detail view of the mechanism for actuating the cash or fare registering devices to register the minimum fare; Fig. 38 is a similar view with the alining pawl in its operative position; Fig. 39 is a detail view of the mechanism for moving the swinging transfer shaft for the trip registering devices; Fig. 40 is a detail view of a similar device for the total registering devices; Fig. 41 is a transverse, sectional view taken through the driver's and cashier's identifying devices and showing the alining pawls for the

respective devices; Fig. 42 is a longitudinal, sectional view, taken through the driver's identifying device; Fig. 43 is a transverse, sectional view taken through that device; Fig. 44 is a detail view of the pawl and ratchet mechanism interposed in the gearing on the worm wheel shaft; Fig. 45 is a detail view of the feed rollers for the cashier's record; Fig. 46 is a detail view of the cam and its coöperating arm forming a part of the resetting device for the cam for the trip mileage registering devices; Fig. 47 is a top, plan view of the mileage counters showing the several shafts spaced apart exaggerated distances; Fig. 48 is an end elevation of the mileage counters and their driving gear; Fig. 49 is a sectional view taken on the line w w of Fig. 47; Fig. 50 is a top, plan view of the several series of groups of counters; Fig. 51 is a sectional view taken on the line A A of Fig. 52 and looking in the direction of the arrows; Fig. 52 is a top plan view of the actuator and its coöperating gearing for actuating the trip cash or fare counters; Fig. 53 is a sectional view taken on the line B B of Fig. 52 and looking in the direction of the arrows; Fig. 54 is a view similar to Fig. 51 with the swinging transfer shafts moved into their outer positions; Fig. 55 is a detail view of the trip cash fare counter and the visual indicator; Fig. 55^a is a detail view of the units counter wheel for the trip cash counter; Fig. 56 is a sectional view taken on the line v v of Fig. 55 and looking in the direction of the arrows; Fig. 57 is a view taken on the line v v of Fig. 55 and looking in the direction opposite that indicated by the arrows; Fig. 58 is a detail view of the trip time counters; Fig. 58^a is a detail of one of the counters shown in Fig. 58; Fig. 58^b is also a detail of one of the counters shown in Fig. 58; Fig. 59 is a sectional view, taken on the line s s of Fig. 58 and looking in the direction of the arrows; Fig. 60 is a top, plan view of the trip numbering mechanism; Fig. 61 is an end elevation of the same; Fig. 62 is a top, plan view, partly in section, of vehicle equipped with the invention, showing the means for delivering the ticket; Fig. 63 is a sectional, detail view of one end of the printing roller and the coöperating cam plate; Fig. 64 is a detail view of the movable member of the cutting devices; Fig. 65 is a view of the ticket for trip No. 1; Fig. 66 is a view of the ticket for trip No. 2; Fig. 67 is a view of a portion of the cashier's record containing the records for the trips Nos. 1 and 2 and the total record for these trips; Fig. 68 is a view of the back of a ticket showing an advertisement thereon; and Fig. 69 is a view of a modified form of ticket.

The machine shown in these drawings illustrates one embodiment of the invention and is designed more particularly for use in connection with that type of motor-driven

passenger vehicle popularly known as a "taxicab". The number and character of the items registered by the machine will, of course, be determined by the character of the service it is to render. The present machine is adapted to register the distance traveled by the vehicle on a given trip, to register the time consumed by that trip and compute from these two items the amount of fare due either at the end of the trip or at any time during the trip. In addition to these three principal items the machine registers the number of pieces of baggage carried on each trip and also two identifying numbers, one the number of the driver in charge of the vehicle and the other the number of the particular trip, the record of which is being registered. Further, the machine is adapted to print two records of the several items so registered. One of these records, which includes all the items registered, is retained in the machine and constitutes the "cashier's record" which is removed from the machine by the cashier, or other authorized agent of the company operating the vehicle, at the end of the day or other suitable period of time. The second record is printed and issued in the form of a ticket and may contain either all of the items registered or any desired part of these items. In the present instance the ticket contains only the amount of the fare due, the number of pieces of baggage carried and the number of the trip. In addition to the registered items the ticket also contains a suitable heading which, in the case of the present machine, includes the name of the company operating the vehicle, the number of the machine and the date on which the ticket was issued. In addition to registering and printing the several items relating to each trip the machine is also adapted to accumulate and print the total record of these several items, this record being printed upon the cashier's record by the cashier at the end of the day, or other period of time determined upon, at which time the record is removed from the machine. The mechanism by means of which these several items are registered, accumulated and printed may be of any suitable character and the mechanism herein shown and described has been chosen for the purpose of illustration only and it will be obvious that it is capable of a very wide range of modification, both in its entirety and in its detail construction. This illustrative machine is shown as comprising a main frame having end members or plates 1 and 2, respectively, which are connected one to the other by a series of longitudinal bars or tie rods, a part of which are indicated by the numeral 3. Mounted within this main frame are three sets of registering devices adapted to register the two trip records and the total record, respectively. These registering devices, as here shown, comprise three series of groups of counters indicated at A, B and C in Fig. 50. The series A registers the items for the cashier's trip record. The series B registers the items for the ticket and the series C accumulates and registers the items for the cashier's total record. Each series, as stated, comprises several groups of counters and each group of counters is adapted to register the record of one particular item of its respective record and, to this end, consists of two or more counters. These counters may be of any suitable character and are here shown as printing counters of a known construction and comprising type wheels or disks having rigidly connected therewith a gear, by means of which movement is imparted to the type wheel or disk. The particular arrangement of the counters and the manner in which they are operated differs in the several groups and these details of construction will be described as each group of counters is reached in the description of the machine as a whole. It may be noted, however, that the three series of groups of counters are mounted on two shafts, the groups A and B being arranged in alinement and mounted on a single shaft 4, while the group C or the total counters are mounted on a second shaft 5 which is preferably arranged in substantially the same horizontal plane with and in the rear of the first shaft. These shafts are preferably what are known as resetting shafts and are here shown as of a well known construction, in which the shaft is normally stationary and the counters rotate about the shaft. (See Figs. 9 to 23.) Each shaft is provided with a series of annular grooves 6, one of which grooves is arranged adjacent to each counter which is to be reset, and the hub of the counter is provided with a pin 7 adapted to enter and travel in the respective groove. The shaft also has a longitudinal slot 8 intersecting the several annular grooves and having mounted therein a bar 9 which has formed in its outer edge a series of notches 10. These notches are arranged to correspond with the arrangement of the annular grooves 6, and, when the bar is in its normal position, the notches 10 register with the grooves 6 and the counters are free to rotate about the shaft. When it is desired to reset the counters to zero, to begin a new record, the bar 9 is shifted longitudinally to the shaft and the notches 10 moved out of alinement with the annular grooves 6. The shaft is then rotated about its longitudinal axis and in the course of its rotation those portions of the bar which extend across the several annular grooves will engage the pins carried by the respective counters and thus pick up the

counters and cause them to rotate with the shaft. When the shaft has been rotated through one complete revolution the counters will all have been returned to their zero 5 position and the slide bar 9 is again moved to its normal position and the operation of registering continues as before.

The device for controlling the position of the slide bar 9 is here shown as consisting 10 of two fixed cam rings 11 and 12 arranged about the opposite ends of the shaft. The cam ring 11 has a recess 13, the walls of which are inclined, while the cam ring 12 has a projection 14 which also has its walls 15 inclined. The recess 13 and the projection 14 are so located that when the resetting shaft is in its normal position these parts will be located at the opposite ends thereof and one end of the shaft will extend into the 20 recess 13 and the other end will be in engagement with the end of the projection 14. When it is desired to reset the counters the shaft is rotated, in a manner hereinafter to be described, and this rotation causes one 25 end of the bar to pass beyond the projection 14 and the other end to ride up the inclined wall of the recess, thereby longitudinally displacing the bar. When the shaft has completed its revolution one end thereof will 30 engage the inclined wall of the projection 14 and will ride up the same, thus forcing the opposite end of the bar into the recess 13 and again bringing the notches 10 into alignment with the grooves 6.

35 The mileage registering mechanism is operated by means of suitable connections with one of the ground wheels of the vehicle (see Fig. 62). This connection is here shown as of a well known form comprising 40 a flexible shaft 15 connected at one end with suitable actuating devices 16 carried by the axle and the hub of the wheel, respectively, and of such a construction that the shaft, preferably, receives one rotation for each 45 complete revolution of the wheel. This mechanism is also of a well known construction and need not be here described in detail. The actuating devices 16 may be connected with any of the ground wheels, but 50 are preferably connected with one of the front wheels, to avoid inaccurate registration which would result from the slipping of the rear wheels, which usually constitute the driving wheels of vehicles of this type. The upper end of the flexible shaft 55 15 is connected with a short shaft 17 (see Figs. 2 and 5) mounted in suitable bearings 18 carried by the main frame of the machine and has rigidly secured to its upper 60 end a worm 19 which meshes with and rotates a worm wheel 20 which constitutes the drive wheel for those parts of the registering mechanism which are controlled by the distance traveled.

65 The worm wheel, or driving wheel, 20 is

loosely mounted upon a normally fixed shaft 21 and is connected by means of suitable clutch mechanism with a gear 22 which is also loosely mounted on the shaft 21. (See Figs. 2, 3 and 4.) This clutch mechanism 70 may be of any suitable character which will permit the drive wheel 20 to rotate in a reverse direction, when the vehicle moves backward, without affecting the gear 22 and the registering mechanism. The form here 75 shown comprises two round nose spring-pressed pawls 23 mounted upon the side of the worm wheel 20 and engaging the periphery of a disk 24 which is rigidly connected with the gear 22. (See Fig. 35.) The gear 80 22 meshes with a pinion 25 which is rigidly secured to a small countershaft 26 rotatably mounted in the end members 1 and 2 of the main frame and extending parallel with the shaft 21. The shaft 26 also has mounted thereon two other pinions of a size corresponding with the pinion 25, as indicated at 27 and 28. One of these pinions, 28, is rigidly secured to the counter-shaft 26 and rotates therewith. The other pinion, 27, is 85 loosely mounted on the shaft 26 and has no rotation therewith save when operatively connected with the pinion 28. The pinion 27 meshes with a gear 29 loosely mounted upon the shaft 21. The gear 29 is of a size 90 and pitch similar to the gear 22 and makes the same number of revolutions as does that gear. The ratio of the worm and worm gear are such that the worm wheel and the gear 22, which is clutched thereto, will make ten 100 revolutions for each mile traveled by the vehicle, and, consequently, the gear 29, which drives the trip mileage registering 105 devices, will likewise make ten revolutions per mile when the pinions 27 and 28 are operatively connected one to the other. This connection may be made in any suitable manner and is preferably such that the gear 29 will rotate when the vehicle contains a passenger and is in actual service, but will 110 remain stationary when the vehicle is running empty, as when it is returning to the cab-stand after having discharged the passenger. As here shown, the connecting device comprises a pinion 30 of sufficient width 115 to mesh simultaneously with both the pinions 27 and 28 and rotatably mounted on a stud 31 carried by an arm 32 which is loosely mounted on a shaft 33 and has rigidly secured thereto, and preferably 120 formed integral therewith, a crank arm 34, which, in turn, is connected to a pitman 35 which is actuated in a manner hereinafter described to rock the arm 32 about its pivotal center. (See Figs. 4 and 27.) The 125 rocking movement of the arm 32 serves to move the pinion 30 into and out of mesh with the pinions 27 and 28 and thus connect and disconnect the actuating mechanism, for the trip mileage registering de- 130

vices, and the wheel drive. The gear 29 is operatively connected with a cam 36 (see Figs. 2, 4 and 27) rotatably mounted on the shaft 21 and operatively connected with a 5 ratchet wheel 37 rotatably mounted upon an intermediate shaft 38. (See Fig. 27.) The intermediate shaft 38 is journaled in the opposite end members 1 and 2 of the main frame, but is held normally against rotation.

10 The connection between the gear 29 and the cam 36 preferably comprises a disk 39 rotatably mounted on the shaft 21 and rigidly connected with the cam 36. The 15 periphery of the disk 39 is engaged by a round nose spring-pressed pawl 40 carried by the gear 29. This connection causes the cam to rotate forwardly with the gear, but permits the cam to rotate forwardly independently 20 of the gear. The nose of the cam 36 is arranged to engage a projection 41 on one arm of a bell crank lever 42 which is journaled upon the intermediate shaft 38. The other arm of the lever 42 has pivotally 25 mounted thereon a pawl 43 having a nose 44 arranged to engage the teeth of the ratchet wheel 37. An arm 45 is connected to the pawl 43 and has secured thereto one end of a spring 46, the other end of which is secured 30 to a fixed part of the machine beyond the nose of the pawl and serves both to move the lever 42 about its axis and to hold the nose of the pawl in engagement with the teeth of the ratchet wheel. Each revolution 35 of the gear 29 will thus cause the cam 36 to actuate the lever 42 against the tension of the spring 46 and retract the pawl 43 a distance sufficient to enable it to engage the next succeeding tooth of the ratchet wheel.

40 When the nose of the cam has passed the projection on the lever the spring 46 will actuate the lever and cause the pawl to move forward, thus actuating the ratchet wheel 37 one step. This ratchet wheel has rigidly 45 secured thereto a driving gear 47 which meshes with a gear 48 loosely mounted upon an actuator shaft 49, which shaft is mounted in the end members 1 and 2 of the main frame, extends parallel with the resetting 50 shafts 4 and 5 and is arranged in a vertical plane extending between the axes of these shafts. The gear 48 is rigidly connected by means of a sleeve or hub 50 with a second gear 51 also loosely mounted on the actuator shaft 49 and the two gears and their connecting hub constitute an actuator for the 55 trip mileage counters as shown in Fig. 47. The gear 51 of the actuator meshes with a loose gear or idler 52 loosely mounted on the trip counter shaft 4, and operatively connected with the unit printing counter 53 of the trip mileage counters. This connection preferably comprises two pairs of gears of different pitch. The gear 52 is a fine tooth 60 gear. This gear meshes with a correspond-

ing gear 54 on a transfer shaft 55. The gear 54 is connected by means of a hub 56 with a coarse tooth gear 57, which, in turn, meshes with a similar gear 58 rigidly secured to the unit counter 53. In the present 70 instance the gears 52 and 54 are twenty tooth gears and the gears 57 and 58 are fifteen tooth gears. In this construction the movement from the actuating gear 51 is transmitted accurately to the unit counter 75 and it is possible to move the fine tooth gears 52 and 54 out of mesh one with the other and reset the counters without affecting the actuating mechanism and further without moving the coarse tooth gears out of mesh 80 one with the other, as is more accurately shown in Fig. 54 in connection with the cash counters. In order that the fine tooth gears may be moved out of mesh one with the other the transfer shaft 55 is a swinging 85 shaft and is supported by links or arms 59 upon a second shaft arranged parallel with the transfer shaft and below the same, as indicated at 60, shown in Figs. 5 and 39. This swinging movement is automatically 90 imparted to the shaft 55 to carry the fine tooth gears out of mesh by the first portion of the movement of the resetting shaft. To this end the arm 59 has a nose 61 which rests normally within a recess 62 formed in a 95 collar or disk 63 rigidly secured to the resetting shaft. As this shaft begins its movement this nose will be forced out of the recess and the desired amount of movement imparted to the shaft 55 and the transfer 100 gears carried thereby. The actuating movement is imparted from the unit counter of the mileage group to the tens counter thereof by any suitable mechanism, and, in the present instance, a common type of 105 transfer mechanism, known as the "Geneva Transfer" is employed. This comprises a one tooth gear secured to the reverse side of the unit counter, as indicated at 64, and meshing with a star wheel 65 carried by the 110 transfer shaft 55. A gear 66 is rigidly connected to the star wheel 65 and meshes with a gear 67 forming a part of the tens counter. The movement is transferred from the tens 115 counter to the hundreds counter and so on in the same manner.

Referring again to Fig. 27 it will be noted that the pawl 43 is provided with a recess 68 having an inclined upper wall adapted to engage the beveled edge of a stop 69, which, in the present instance, constitutes one of the tie bars for the main frame of the machine. This stop serves to positively limit the forward movement of the lever 42 and the pawl 43, and, at the same time, the 120 beveled edge of the stop engaging the inclined wall of the recess 68 lifts the nose 44 of the pawl out of engagement with the base of the tooth of the ratchet wheel and leaves the ratchet wheel free to be adjusted to bring 125

130

the printing counters into proper printing alinement. At the same time the stop 69 serves to prevent the nose of the pawl from moving entirely out of engagement with the 5 teeth of the ratchet wheel, but retains the same in position to engage the following tooth and prevent the same from running past the pawl. The means for adjusting the ratchet wheel to bring the printing counters 10 into printing alinement, in the present instance, comprises an alining pawl 70 which is mounted on the shaft 33 and has a finger 71 which is connected to one end of a spring 72, the opposite end of which is connected 15 to a fixed part of the machine, such as the bar 69, and thus tends to hold the nose of the pawl 70 in engagement with the ratchet wheel. The nose of this pawl is shaped to fit snugly between the teeth of the ratchet 20 wheel and the pressure of the spring 72 will force the nose of the pawl against the inclined side of the adjacent tooth and thus adjust the wheel to bring the counters into printing alinement. This pawl also serves 25 as a retaining pawl to prevent the accidental displacement of the ratchet wheel, and, consequently, of the counters.

The cam operating mechanism for the trip mileage counters advances these counters 30 a very considerable fraction of a mile upon each revolution of the cam. In the present instance the cam, together with the actuating gear, makes ten revolutions per mile, and, consequently, the counters are advanced 35 one-tenth of a mile at each step. It will frequently happen in the use of the machine that when the trip is ended and the passenger discharged the cam 36 will have completed a partial revolution. If the cam 40 remains in this position until the vehicle is again hired the second passenger will be charged with a fraction of a mile which he did not ride. Consequently, it is necessary that the cam should be reset to its normal or 45 zero position each time the trip counters are reset to zero. To this end the disk 39, which is rigidly secured to the cam, has mounted thereon a spring-pressed pawl 74 arranged to engage a one-tooth disk 75 50 rigidly secured to the worm wheel shaft 21. A single complete revolution is imparted to the worm wheel shaft 21 each time the trip counters are reset to zero, this being accomplished in a manner hereinafter described. Upon this movement of the shaft 55 21 the tooth of the disk 75 will pick up the pawl 74 regardless of the position of the cam and move the cam to its normal position. This movement, however, will cause the cam 60 to engage and operate the lever 42 carrying the pawl 43, and, as this movement does not represent the distance traveled, it is necessary to provide some means to prevent this movement of the lever and pawl from actuating 65 the ratchet wheel 37 and the mileage

counter. In the present instance means are provided for holding the nose of the pawl out of engagement with the ratchet wheel during the operative portion of its stroke. To this end the pawl 43 is provided with a 70 tail 76 and an arm 77 is mounted upon a shaft 78 and is supported normally in a position in which its nose will not engage the tail of the pawl. But when the shaft 21 is actuated the arm 77 will be moved into 75 such a position that it will be engaged by the tail of the pawl and will raise the nose of the pawl out of engagement with the ratchet wheel and hold the same out of engagement therewith during 80 the operative portion of its stroke. The arm 77 is held normally in its inoperative position by means of a spring 79 connected at one end to a finger 80, rigidly connected with the arm 77, and at the other end 85 with a finger 81 rigidly connected to a second arm 82 mounted on a shaft 83. An arm 84 mounted on the shaft 78 and rigidly connected to the arm 77 has at its free end a nose 85 arranged to ride over the periphery 90 of the disk 73 and to engage a cut away portion or elongated recess formed in one side of that disk, as indicated at 86 in Fig. 46. This cut away portion is so arranged in the disk 73 that normally the nose 85 of the arm 95 84 will extend into the recess and the spring 79 will retain the arm 77 in its inoperative position. At the beginning of the rotation of the shaft 21, however, the recess will pass beyond the nose of the arm 84 and this arm 100 and the arm 77, to which it is secured, will be rocked about their pivotal center on the shaft 78, thereby bringing the nose of the arm 77 into position to engage the tail 76 of the pawl. The arm 77 also has rigidly 105 secured thereto a finger 87 having a lateral projection 88 which extends across the inner edge of the arm 82, which arm is provided with a shoulder 89. When the parts are in their normal positions the projection 88 of 110 the finger 87 will engage the arm 82 above the shoulder 89. The movement of the arm 77 about its pivotal center will move the projection 88 below the shoulder 89 and the spring 79 will throw the arm 82 forward and 115 cause the shoulder to engage the upper edge of the projection thus locking the arm 77 in its operative position regardless of the position of the disk 73. The inner end of the arm 82 extends in the path of a toe 89^a carried by the end of the lever 42. When the shaft 21 has completed its movement and the nose of the cam has been returned to its normal position the projection 41 of the lever 42 will move inwardly under the tension of the spring 46. This movement of the lever 42 will cause the toe 89^a to engage the inner end of the arm 82, moving the same about its pivotal center on the shaft 83 and permitting the spring 79 to again move the 120 125 130

arm 77 about its pivotal center and into its inoperative position.

In the present machine the total mileage instead of including merely the total mileage for the day, or period of time covered by the cashier's record, includes the grand total mileage for the vehicle and shows the total distance traveled by the vehicle since it went into service or since some other fixed date. Consequently, the registering mechanism for the total mileage is never reset. The trip mileage registering mechanism is preferably reset to zero each time the flag is returned to its normal or "for hire" position. To avoid inaccuracies due to the re-setting of the trip mileage actuating cam the total mileage registering mechanism is entirely separate from the trip mileage, although in its construction and operation it is quite similar to the trip mileage registering mechanism. The shaft 26 which receives its movement from the driving wheel 20 has rigidly secured thereto a pinion 90 similar to the pinions 25, 27 and 28. (See Fig. 28.) This pinion meshes with a gear 91 mounted on the shaft 21 and having rigidly secured thereto a cam 92 which is arranged to engage a projection 93 carried by one arm of a bell crank lever 94 mounted upon the shaft 38. The other arm of the bell crank lever 94 has a pawl 95 similar in construction and operation to the pawl 43 of the trip mileage mechanism. This pawl meshes with the teeth of a ratchet wheel 96 mounted on the shaft 38 and rigidly secured to a driving gear 97 which meshes with an actuating gear 98 mounted on the actuator shaft 49 and meshing with a loose gear 99 on the rear counter shaft 5, which gear is a fine tooth gear and meshes with a corresponding fine tooth gear 100 mounted on a rear swinging transfer shaft 101. The fine tooth gear 100 is rigidly connected with a coarse tooth gear 102 which meshes with a similar gear 103 rigidly secured to the units total mileage counter 104. The transfer mechanism from the units to the succeeding printing counters is the same as that described in connection with the trip mileage counters. Although the total mileage counters are never reset it is necessary that they be provided with fine and coarse tooth driving gears to permit the transfer shaft which carries the transfer gears for the other total counters to be moved outward without moving the several transfer gears out of engagement with the counter gears for the total mileage, but always retaining these in engagement and preventing any displacement of the counters. The rear swinging transfer shaft is carried by arms 107 Figs. 34 and 40 mounted upon a shaft 108 and the swinging movement is imparted to the shaft 101 by a nose 109 carried by one of the arms 107 and engaging a recess 110 in a disk 111 carried by the rear

counter shaft 5, in the same manner as movement is imparted to the front swinging transfer shaft. An alining pawl 105, similar to the alining pawl 70 for the trip mileage mechanism, is mounted on the shaft 70 33 and is held normally in engagement with the ratchet by means of a spring 106. This pawl serves both to adjust the ratchet wheel to move the printing counters into their printing positions and to retain the ratchet 75 against accidental movement.

The cash or fare registering mechanism is controlled both by the distance traveled by the vehicle or mileage and by the time consumed by the trip. The gear 22, which is 80 clutched to the worm wheel or driving wheel 20, has rigidly secured thereto a gear 112 of smaller diameter which is loosely mounted on the worm wheel shaft 21 and meshes with a gear 113 on the intermediate shaft 38. 85 The gear 113 has rigidly secured thereto a smaller gear 114 which meshes with a large gear 115 on the worm wheel shaft 21, which, in turn, has connected thereto a smaller gear 116 meshing with a large gear 117 on the intermediate shaft. The movement is transferred in this manner from the worm wheel shaft 21 to the intermediate shaft and back a sufficient number of times to reduce the number of revolutions made by the last gear 95 117^a on the worm wheel shaft to 8-30ths of a revolution for each mile traveled by the vehicle as compared with the ten revolutions per mile made by the gear 22. The last of these reducing gears, 117^a, is connected by a 100 sleeve 118 with an arm 119, (see Fig. 44), carrying a spring-pressed pawl 120 which co-operates with a fine tooth ratchet wheel 121 rotatably mounted on the worm wheel shaft 21.

The wheel 121 is connected by a sleeve or hub 122 with a gear 123, which gear meshes with a corresponding gear 124 loosely mounted on the intermediate shaft 38. The gear 124 carries on one side thereof (see 110 Fig. 30) a spring-pressed pawl 125 arranged to engage a one tooth ratchet wheel 126 which is connected by means of a sleeve 127 with a gear 128 of large diameter. This gear 128 is a continuously rotating gear, its 115 rotation being received from the wheels of the vehicle, in the manner just described, when the speed of the vehicle exceeds a certain predetermined minimum rate, which, in the present instance, is three and three-fourths miles per hour. When the speed of the vehicle is less than this predetermined rate the gear 128 is rotated by suitable clock mechanism, and, to this end, the gear 124 is rigidly connected to a ratchet wheel 129 120 adapted to be engaged and actuated by a pawl 130 carried by a large gear 131 which is loosely mounted upon the intermediate shaft 38 and constitutes a driving gear for the time registering devices, to be herein- 130

after described (see Fig. 31). This gear has rigidly secured thereto a bevel gear 132 meshing with a second bevel gear 133 carried by a shaft 134 forming part of the 5 clock mechanism, indicated as a whole at 135 and having its dial arranged to indicate the time on the face of the machine. (See Figs. 1 and 5.) When the vehicle is in motion and the speed exceeds the minimum 10 speed the gear 124, and consequently, the gear 128, to which it is connected, will be rotated by the gear 123, which is actuated from one of the wheels of the vehicle, and the ratchet wheel 129 which is secured 15 to the gear 124 will run ahead of its pawl. When the vehicle is standing still or moving at a rate lower than the minimum rate the gear 124 will be driven from the clock mechanism, through the gear 131 and the 20 pawl and ratchet wheel 130 and 129, and the ratchet wheel 119 on the shaft 21 will run ahead of its pawl. Loosely mounted on the shaft 38 is a large gear 138 which constitutes the driving gear for the cash or 25 fare counters. This gear is driven from the continuously rotating gear 128 and may be connected with that gear in any suitable manner so long as the connection is such that the two gears may be connected during 30 the "live time", or the time the vehicle is engaged, and may be disconnected during the "dead time", or the time when the vehicle is unengaged. In the present instance the two gears 128 and 138 are mounted close 35 together on the shaft 38 and each meshes with a pinion mounted on a shaft 139. One of these pinions, 140, is loosely mounted on the shaft 139 and meshes with the gear 128, while the second pinion, 141, is rigidly 40 secured to the shaft 139 and meshes with the gear 138. A connecting pinion 142 of a width sufficient to enable it to mesh simultaneously with both the pinions 140 and 141 is rotatably mounted on a stud 143 carried 45 by an arm 144, which arm is rigidly secured to a shaft 145. The shaft 145 is rocked about its longitudinal axis to move the connecting pinion 142 into and out of mesh with the pinions 140 and 141, at the beginning 50 and end, respectively, of the trip in the manner hereinafter to be described.

The large gear 138 serves to drive the cash or fare counters for the cashier's records, both trip and total. (See Figs. 51 to 55 57.) These counters are in many respects similar to those described in connection with the mileage registering devices, but their detail arrangement differs from the mileage counters. The gear 138 meshes with 60 an actuator 146 rotatably mounted upon the actuator shaft 49 and retained against longitudinal movement in one direction by a collar 147. This actuator meshes with loose gears or idlers 148 and 149 mounted 65 on the front and rear counter shafts 4 and

5, respectively. These idlers are fine tooth gears, having preferably twenty teeth each, and mesh with corresponding gears 150 on the transfer shafts 55 and 101, respectively. Rigidly secured to the gear 150 are coarse tooth gears 151, preferably having fifteen teeth, which mesh with corresponding gears 152 forming parts of the unit counters for the trip and total cash records, respectively. It is understood, of course, that the front and rear shafts 4 and 5 are reset independently and that when either is reset the swinging transfer shaft is moved outward, in the manner above described, a distance sufficient to disengage the fine tooth gears, but to retain the coarse tooth gears in mesh, as indicated in Fig. 54, thus permitting the counters to be reset without affecting the actuator 146. The cash is registered in the multiples of five and the units counter 153, as shown in Fig. 55, has a ten point counter having the numerals 5 and 0 arranged alternately thereon. In order that this units counter may transfer one count to the tens counter each time ten cents has been registered it is provided on its inner side with a five point transfer gear 154 of a known type, which meshes with a ten point star wheel 155 on the transfer shaft and thus advances the tens counter one step for every two steps of the units counter. The remaining portions of the transfer mechanism are of ordinary construction and need no description and it will be understood that this mechanism, which is here described in connection with the trip cash registering mechanism, is duplicated in connection with the total cash registering mechanism.

The cash counters for the ticket are similar in their construction and operation to those just described for the cashier's record except that they are of greater width and the type carried thereby is larger. To operate the ticket cash counters in unison with the cashier's record counters a pinion 156 is 105 rigidly secured to the shaft 139 and meshes with a driving gear 157 mounted upon the intermediate shaft 38. This gear 157 constitutes the driving gear for the ticket cash counters and, to this end, meshes with an 110 actuator corresponding to the actuator 146 of Fig. 51.

In hiring vehicles of the type with which the present machine is employed it is customary to charge a fixed fare for any trip 115 not exceeding a certain predetermined distance or duration. In the present instance this fixed or minimum fare equals the regular fare for a trip of one-half mile or sixteen minutes' duration, which, at prevailing 120 rates, would be forty cents. It is desirable, therefore, that the machine be provided with means for causing the cash registering devices for the several records to register the amount of the minimum fare, 40 cents, at 125 130

the beginning of each trip and that these devices be further controlled to prevent them from registering any further amounts until the amount of the actual fare for the distance traveled or time consumed equals the amount of the minimum fare. These results may be accomplished in any suitable manner, but the registering devices are preferably controlled by the same mechanism that

5 connects and disconnects the several registering devices and their operating mechanisms. In the present instance both the minimum fare actuating devices and the connecting devices are controlled by the movement of a signal or flag, which, when in one position, indicates that the vehicle is empty and "for hire" and which, when in another position, indicates that the vehicle is "engaged." The signal or flag may be of

10 any suitable character and it may be connected with the devices to be controlled thereby in any suitable manner. In the accompanying drawings the flag is shown as comprising a flag or signal proper 159 which is carried by an arm or lever 160 forming a part thereof. The term "flag" as herein-after used will include both the signal proper and the arm or lever which carries the same. This flag is mounted upon the

15 outer end of a sleeve 161, which sleeve is journaled upon a hollow stud 162 rigidly secured to the end member 1 of the main frame in alignment with the intermediate shaft 38 and preferably adapted to receive the end of that shaft (see Figs. 3 and 14). The sleeve 161 extends through and beyond the cabinet 163, which incloses the machine as a whole, and the flag is mounted upon the sleeve on the outside of said cabinet. The

20 several parts operated thereby are arranged within the cabinet and are inaccessible when the cabinet is in position. Rigidly secured to the sleeve 161, Figs. 14 and 18, is an arm 164 having a pin 165 which extends into the slotted end of a second arm 166. This second arm is rigidly secured to the outer end of a short shaft 167 which is mounted in a bearing 168 carried by the frame member 1, extends through that frame member and has

25 rigidly secured thereto within the frame member a toothed segment 169 provided with an extension 170 having a notch 171 formed in the periphery thereof. The toothed segment 169 meshes with a gear 172

30 loosely mounted on the intermediate shaft 38. This gear is rigidly connected, preferably by means of a sleeve, with an arm 173, Figs. 4, 37 and 38, which has on its outer end a stud 174 on which is mounted a pawl

35 175. The pawl 175 has a laterally extending projection 176 arranged to engage the teeth of a ratchet wheel 177 loosely mounted on the intermediate shaft 38 and rigidly connected with the driving gear 157 for the

40 ticket cash counters. This gear is, as above described, connected by means of a pinion 156 on the rotatable shaft 139 and a pinion 141 also on the shaft 139 with the driving gear 138 for the cash counters for the cashier's record. Thus, it will be apparent that the movement of the flag from its normal or "for hire" position, which, in the present instance, is substantially vertical, into its "engaged" position will actuate the ratchet wheel, and, consequently, both the ticket

45 cash counters and the trip and total cash counters of the cashier's record. The movement of the flag is approximately one-fourth of a revolution and this movement is sufficient to advance the cash counters forty cents, the amount of the minimum fare. The projection 176 of the pawl 175 is normally out of engagement with the ratchet wheel 177, and, in the normal operation of the machine, offers no resistance to the movement of the ratchet or driving gear. It is held in its inoperative position by means of a spring 178 connected at one end to the arm 173 and at the other end to a crank arm 179 mounted on the stud 174 and rigidly connected to the pawl 175, the arrangement of the crank arm relative to the pawl being such that the tension of the spring will tend to move the projection carried by the pawl away from the ratchet teeth. Obviously, with the pawl held normally out of engagement with the ratchet wheel the movement of the arm 173 will not actuate the ratchet and it is necessary to provide some means for moving the pawl into operative engagement with the ratchet wheel when the flag is moved into its engaged position. To this end the pawl 175 has a second projection 180 which is preferably provided with a roller and extends from that side of the pawl opposite the projection 176.

50 Arranged in the path of the projection 180 is a guide cam 181 which is supported from the end member 1 upon studs 182, which studs support the guide at a sufficient distance from the side of the plate to permit the segment 169 to move between the guide and the frame member. That end of the guide or cam 181 adjacent to the pawl 175 is outwardly inclined, as shown at 183. When the arm 173 and the pawl 175 are moved forward under the influence of the flag the projection 180 will engage the inclined end portion of the guide and will be moved inward, thus carrying the projection 176 of the pawl into engagement with the teeth of the ratchet wheel, in which position it is held by the cam or guide during the continued movement of the flag Figs. 37 and 38. The length of the guide or cam 181 is such that the projection 180 will pass beyond the end of the same just prior to the end of the movement of the flag and the spring 178 will move the pawl out of engagement with the teeth of the ratchet

55 130

wheel 177. So long as the flag remains in its "engaged" position the pawl 175 will remain in its inoperative position at the lower end of the guide 181, in which position it has no effect upon the operation of the driving gears. When the flag is returned to its normal or "for hire" position the stud or projection 180 will engage the beveled lower end of the guide 181 and will ride over that guide, thus retaining the pawl out of engagement with the ratchet wheel during its return to normal position. The present machine, as above described, is designed to register a minimum fare of forty cents, but it will be obvious that by varying the length of the cam or guide 181 the amount of this minimum fare can be increased or decreased.

It will be apparent that the movement of the ratchet wheel under the influence of the flag will, through the gearing above described, cause the one tooth ratchet wheel 126 to run ahead of its pawl 125. Should the amount of the actual fare for the trip, based upon the time and distance, be less than the amount of minimum fare the ratchet wheel 126 would still be in advance of its pawl at the beginning of the next trip. As a result the second passenger would receive more than he paid for, either in time or in distance. Suitable mechanism is, therefore, provided for moving the ratchet wheel into engagement with its pawl when the flag is returned to its "for hire" position. This mechanism comprises a second pawl 184 mounted on the stud 174 carried by the arm 173 and having a friction nose arranged to engage the inner surface of an annular flange 185 secured to one side of the ratchet wheel 177. The pawl 184 is connected to the pawl 175 by a spring 186. When the arm 173 is in either its normal, or upper, position or is in its lower, or "engaged," position both the pawls 184 and 175 will be out of engagement with their respective parts of the ratchet wheel. When the flag and the arm 173 are returned to their normal positions and the projection 180 of the pawl 175 rides over the guide 181 the nose of the pawl 184 will be moved into frictional engagement with the flange 185. This frictional contact, while light, is sufficient to rotate the ratchet wheel in a reverse direction, and, consequently, to rotate in a reverse direction the several parts connected with the ratchet wheel, thus carrying the ratchet wheel 126 back into engagement with its pawl 125. As soon as the tooth of the ratchet wheel engages the pawl the movement of the ratchet wheel will be checked and the pawl 184 will slip over the inner surface of the flange 185 and thus permit the arm 173 to return to its normal position without affecting the positions of the gears 124 and 123.

In the operation of a machine of this character it will, of course, frequently happen

that at the end of a trip the registering devices will have completed but a portion of the unit which they register, that is, the cash counters will not have advanced far enough to bring the type into position to print the next unit. Consequently, an alining device is provided which will engage the ratchet wheel 177 prior to the printing operation and will cause the same to complete the step which has been partially completed. For example, if the machine has run between eight tenths and nine tenths of a mile, the alining device will cause the cash counters to register the fare for a full nine tenths of a mile, and, if the vehicle has been waiting one minute, then the alining device will cause the cash counters to register the fare for the full two minutes. This alining device comprises a pawl 187, Figs. 2, 37 and 38, pivotally mounted on the outer end of an arm 188 carried by the rock-shaft 33, which is rocked in the manner hereinafter described. A finger 189 is rigidly connected with the pawl 187 and has connected thereto one end of a spring 190, the opposite end of which is secured to a finger 191 rigidly connected with the arm 188. The movement of the pawl about its pivotal center under the tension of the spring 190 is limited by a second finger 192 rigidly connected to the pawl and adapted to engage a pin 193 carried by the arm 188. When a rocking movement is imparted to the shaft 33 in a manner to be described the arm 188 and the pawl carried thereby will be moved toward the ratchet wheel 177 and the nose of the pawl will engage the adjacent tooth of the ratchet wheel and move the same forward far enough to carry the units printing wheel into its proper printing position and will then be withdrawn into such a position that it will not interfere with the further operation of the ratchet wheel.

The movement of the flag into its "engaged" position also connects the cash or fare counters and the trip mileage counters with their respective actuating mechanism. As has been above explained the connecting devices for the fare counters or registering device comprises a pinion 142 carried by the arm 144, which arm is rigidly secured to the shaft 145. The connecting device for the trip mileage counters also includes a wide pinion carried by the arm 32 pivotally mounted on the rockshaft 33. (See Figs. 5, 18 and 29). The arm 32 is connected by means of the crank arm 34, the pitman 35 and a second crank arm 194 with the shaft 145. The rocking movement which actuates these several parts is imparted to the rockshaft 145 through the medium of an arm 195 rigidly secured thereto and having a laterally extending projection 196, which, when the flag is in its raised or "for hire" position, rests in the notch 171 in the cam 130.

extension 170 of the segment 169. The arm 195 is retained in this position by means of a spring 197 connected at one end to the arm and at the other end to a fixed part of the machine. When in this position the connecting pinions 143 and 30 are supported in their inoperative positions. The first movement of the flag moves the notch 171 of the cam extension 170 beyond the projection 196 and causes this projection to ride over the higher portion of the cam extension, thereby rocking the shaft 145 and moving the several parts connected thereto into their operative positions. A spring 198 is here shown as connected to a fixed part of the machine, such as the clock frame, and having a nose adapted to engage the teeth of the connecting pawl 143 to hold these teeth in proper position to mesh with the teeth of the pinions 140 and 141. It is also desirable that means should be provided to make it necessary to move the flag through a complete stroke in one direction before it can be moved in the opposite direction, thus preventing the return of the flag to its original position before the several parts controlled thereby have completed their operations. This is accomplished, in the present machine, by an arrester comprising a toothed segment 199 carried by the outer end of an arm 200 which is mounted on the stud 162 and rigidly connected with the flag and is, in the present instance, formed integral with the arm 164. A pawl 201 is mounted on the end frame of the machine and is held normally in a substantially radial position relatively to the stud on which the arrester is mounted by means of a spring 202. The toothed segment 199 of the arrester is of such a length that when the flag is in either its "engaged" or "for hire" position the segment will lie on one side or the other of the pawl and the pawl will be retained in its normal position. During its movement from one position to the other the segment will engage the pawl and move the same out of its radial position and the pawl will ride over the teeth of the segment until the segment has completed its movement, when it will again assume its normal position. While the pawl is in engagement with the teeth of the segment it will effectually prevent any attempt to move the segment, or the flag to which it is connected, in a reverse direction, that is, in a direction opposite the direction in which it is started, thus necessitating the completion of the movement of the flag.

The resetting of the trip counters to zero at the end of each trip is preferably accomplished by the return of the flag to its normal or "for hire" position. Further, it is desirable that this return movement of the flag should also reset to zero the actuating cam for the trip mileage counters. While

this may be accomplished in various manners, in the present machine (Figs. 6, 14, 15 and 15^a), a four toothed ratchet wheel or notched disk 203 is rotatably mounted on the hollow stud 162 and is adapted to be 70 engaged by a spring-pressed pawl 204 carried by an arm 205 which is rigidly connected with the flag and, in the present instance, is formed integral with the arrester arm 200 and the arm 164. The arrangement 75 of this pawl and of the teeth or notches of the disk 203 is such that on the forward movement of the flag and the arm 205 the pawl will ride over the teeth of the disk, but upon the return of the flag to its normal position the pawl will engage the adjacent tooth of the disk and cause the latter to rotate through a quarter of a revolution. A pawl 422 is mounted on the end member 85 of the main frame, preferably on the stud carrying the arrester pawl 201, and is arranged to engage the teeth of the disk 203 and hold the latter against rearward movement. The forward end of the pawl 204 has its outer edge inclined to form a shoulder which is adapted to engage a suitable stop to prevent the overthrow of the pawl and the four-toothed disk and positively limit the movement of the disk to a quarter 90 of a revolution. This stop may be of any suitable character, but, in the present instance, comprises the end of the worm wheel shaft 21 which projects beyond the end member of the main frame, as indicated at 95 21 in Fig. 15^a.

Rigidly connected with the disk 203 and preferably mounted on the hub thereof are two gears 206 and 207, the gear 206 being of a larger diameter than the gear 207. This larger gear 206 meshes with a pinion 208 105 loosely mounted on the actuator shaft 49, which extends beyond the adjacent end member 1 of the main frame, and having pinned thereto a second pinion 208^a which meshes with a gear 209 rigidly secured to 110 the outer end of the front counter shaft or resetting shaft 4. As here shown the ratio of the several gears is such that a quarter of a revolution imparted to the disk will impart a complete revolution to the gear 209 115 on the resetting shaft and thus completely rotate that shaft and reset the counters thereon to zero. The smaller gear 207 meshes with a pinion 210 loosely mounted on a stud 211 mounted in the frame end member 1. This idler, in turn, meshes with a pinion 212 rigidly secured to the worm wheel shaft 21. The ratio of these several gears also is such that a quarter revolution of the disk will impart a complete revolution to 120 the gear 212 and to the worm wheel shaft, thus resetting the actuating cam for the trip mileage counters to zero in the manner herefore explained.

The flag is locked against movement by 125

two separate and distinct locking devices, one of which is controlled by the driver and the other of which is controlled by the printing mechanism. The first of these devices, 5 that is, the one controlled by the driver, is adapted to be actuated by a key which cooperates with suitable printing wheels mounted in the machine to set these wheels to print the number on the key, which number 10 is the driver's number. This mechanism constitutes an identifying device, which is well known in fare registers. The device is illustrated in Figs. 42 and 43 and, as here shown, comprises a series of type wheels 213, 15 each of which has secured thereto a disk 214 having an annular series of notches 215. A spring-pressed pawl 216 is provided for each disk and has a nose adapted to fit within the V-shaped notches and to aline the printing 20 disk and retain the same in printing position. Each of the disks 214 has an internal series of teeth, as indicated at 217, there being one tooth for each numeral on the periphery of the printing wheel. Each driver 25 is provided with a key 218 adapted to be inserted in a key barrel 219 mounted in the end frame member and extending into an opening in the cabinet 163. Each key is provided with a number of teeth 220 corresponding to the number of type wheels comprising the number printing device, there being usually three of these type wheels. 30 When the key is inserted in its barrel and rotated each tooth will engage one of the notches 217 of its respective disk and will rotate the corresponding type wheel. The particular notch 217 of the disk which is engaged, and, consequently, the particular numeral which the type disk is set to print depend upon the length of the particular tooth 35 of the key engaged. Pivotaly mounted on the adjacent end member of the main frame is a curved arm 221, (see Fig. 8), which extends about the key barrel and is connected 40 at the end opposite its pivotal connection to the frame to a pitman 222 which is connected at its opposite end to a crank arm 223 rigidly secured to a shaft 224. The key 218 is provided with a notch 225 arranged 45 to receive the edge of the arm 221 when the key is rotated. The arm is provided, however, with a projection 226 which is engaged by the key in the course of its revolution. This engagement serves to move the arm 221 50 about its pivotal center and rock the shaft 224. The shaft 224 extends through the entire length of the machine and has mounted on its opposite end, beyond the frame member 1, a pawl 227 having an inturned nose 55 adapted to enter a notch 228 formed in a disk 229 rigidly secured to the sleeve 162 which carries the flag. This pawl locks the disk and the flag against movement until the driver's key has been inserted and rotated a 60 distance sufficient to set the type wheels of

the identifying device to print his number. A lug 230 is formed on the edge of the arm 221 near the projection 226 and between the same and the pivotal center of the arm. The height of this lug is such that, when 70 the pawl 227 is in engagement with the disk 229, the driver's key will just clear the edge of the lug. The further movement of the key causes it to engage the projection 226 and lift the arm 221 to move the pawl out of 75 engagement with the disk and also to lift the lug 230 into a position in the rear of the key. The projection 226 limits the forward movement of the key and rearward movement thereof causes it to engage the lug 230 80 and move the pawl into engagement with the disk, thus locking the flag when the key is removed and preventing the removal of the key until the flag is in its normal position. 85

A visual fare indicator is also provided and is arranged in such a position as to be visible to the passenger and to indicate the amount of fare due at all times during the trip. (See Figs. 10, 12 and 13.) The visual 90 indicator, as here shown, comprises a series of counter wheels 231 loosely mounted on a shaft 232, which shaft extends substantially parallel with the transfer shaft for the trip counters and is preferably supported in the 95 arms or plates 59, in which said transfer shaft is mounted.

The counter wheels of the visual indicator are preferably arranged adjacent to the fare printing wheels for the ticket printing devices which are here indicated at 233. Each indicator wheel 231 has rigidly secured thereto a gear 234 which is a coarse tooth gear and is connected through the medium of an idle gear 235 loosely mounted on 100 the shaft 55 with the coarse tooth gear 236 rigidly secured to the corresponding ticket printing counter. By means of this connection each of the indicator wheels is driven independently of the other indicator wheels 110 from the corresponding printing wheel of the fare printing counters for the ticket. The connection between the printing wheels and the indicator wheels is made by means of large tooth gears and, consequently, when 115 the transfer shaft 55, on which the intermediate gears 235 are mounted, is swung outward to permit the ticket printing counters to be reset to zero, the gear 235 will not move out of mesh with the gear 236, and, consequently, the indicator wheels will be reset simultaneously with the resetting of the type counters. 120

The time registering devices are arranged to register and print the time at which any 125 record is printed. Thus, the cashier's record of each trip will show the time at which the vehicle was hired and the time at which the passenger was discharged and his daily total record will indicate the time at which 130

that record was taken, which would usually be the time that the vehicle returned to the garage. The time counters are driven from the clock mechanism through the driving gear 131, hereinbefore referred to, which meshes with an idler 237, Fig. 31, mounted upon the actuator shaft 49 which, in turn, meshes with idle gears 238 mounted upon both the front and rear counter shafts. The 5 time counters for the trip and total records are exactly the same so that it is necessary to describe but one of them. The gear 238, which is loosely mounted upon the counter shaft 4, meshes with a corresponding gear 239 on the transfer shaft 55. The gear 239 has rigidly secured thereto a gear 240 which meshes with a gear 241 rigidly secured to the unit printing wheel of the time counters. These gears are fine and coarse tooth gears 10 and of the same character as was described in connection with the cash and mileage counters and the time counters are actuated in the same manner as are the cash and mileage counters. The first or unit's counter 242 of the time group is a ten point counter, but, inasmuch as the time is registered in units of two minutes each this ten point counter is provided with two series of numerals, 0, 2, 4, 6 and 8. Rigidly secured 15 to the inner face of the gear is a two toothed gear 243 which meshes with a twelve point star wheel 244 on the transfer shaft 55. This twelve point star wheel has rigidly secured thereto a gear 244^a which meshes with a gear 245 rigidly secured to the ten's counter 246. Consequently, the ten's counter will be advanced two steps for each revolution of the unit's counter. The ten's counter is a twelve point wheel and bears two series of the numerals 0 to 5, inclusive. The 20 ten's wheel 246 has rigidly secured to the side thereof opposite the gear 245 a two toothed gear 247 which meshes with a twelve point star wheel 248 on the transfer shaft 55. This star wheel has rigidly secured thereto a gear 249 which meshes with a gear 250 on the third counter or hour wheel 251. The hour wheel is a twelve point wheel and carries the numerals 1 to 12, inclusive. 25 It will be apparent, therefore, that the clock mechanism will rotate the unit's wheel 242 continuously and that one of the numerals of that wheel will be moved into printing position every two minutes. For every ten minutes registered by the unit's wheel the ten's wheel is advanced one step. The two gears 242 and 246 will thus register the minutes up to sixty, when one hour will be transferred to the hour wheel 251. 30 Trip counting devices are provided to register and print the number of the trip, the record of which is being registered. This trip counting mechanism may be operated in any suitable manner, but is preferably actuated by the resetting of the trip 35 counter shaft, and preferably the unit wheels of the trip counters are so positioned relatively to the other counters on the counter shafts that, when said other counters are set at zero, the trip number counters will be 70 set at one. Thus, when the zero record is printed for the first trip the number 1 will be printed in its proper place. By referring to the tickets and records it will be noted that the trip numbers are printed on the inner sides of the tickets and the records, and the trip counters for the ticket and the trip cashier's trip record are shown as arranged at the ends of their respective series of groups. The trip counter for the total cashier's record is arranged immediately in the 75 rear of the counters for the trip cashier's record. 40 In Figs. 60 and 61 is illustrated one form of mechanism by means of which the trip numbers may be accurately registered and printed. As here shown, the front or trip counter shaft 4 has rigidly secured thereto a two-tooth gear 252 which is arranged to mesh with a pinion 253 journaled on a stud 254 mounted in a frame or bracket 255, which frame is mounted upon the rear counter shaft 5 and the actuator shaft 49. The pinion 253 is of considerable width and meshes with both the gear 256 of the unit's counter 257 of the trip counters for the front counter shaft and with the gear 258 of the unit's counter 259 of the trip counters for the rear counter-shaft 5, and advances each of these counters one step for each complete revolution of the front or trip counter shaft 4. The gear 258 of the unit's counter on the rear counter shaft meshes with a gear 260 rigidly secured to a sleeve 261 which is 45 loosely mounted on the shaft 108 arranged in the rear of and extending substantially parallel with the rear counter shaft. A second gear 262 is rigidly secured to the sleeve 261 and meshes with a gear 263 loosely mounted on the rear counter shaft 5 and 50 meshing, in turn, with a gear 264 loosely mounted on the actuator shaft 49. The gear 264 meshes with a gear 265 rigidly secured to the unit's counter wheel 266 of the trip number counters for the ticket. The counter 55 wheels are ten point wheels but have twenty point gears and it is, therefore, necessary to move the gears through two points to move the counter wheels one point. It is for this reason that the actuator gear 252 on the resetting shaft has two teeth, each of which meshes with the pinion 253 upon each revolution of the resetting shaft. The count is 60 transferred from the unit's counter 259 on the rear shaft to the ten's counter 267 on the rear shaft by a "Geneva transfer" of ordinary construction, as indicated at 268. The gear 269 of the ten's counter 267 for the rear shaft meshes with a pinion 270 mounted on the stud 254 which carries the pinion 253. 65

The pinion 270 meshes with a gear 271 rigidly secured to the ten's counter 272 of the trip counters for the cashier's trip record. The gear 271 also meshes with a gear 273 rigidly secured to a sleeve 274 loosely mounted on the shaft 60, arranged parallel with and in front of the front counter shaft 4. This sleeve has rigidly secured thereto a second gear 275 which 5 meshes with a gear 276 rigidly secured to the ten's counter wheel 277 for the trip counters for the ticket. Suitable registering devices are also provided to register and print the number of pieces of baggage carried. These 10 devices are so arranged as to be manually operated by the driver independently of the registering devices, and, in the present instance, the charge for the baggage is not added into the fare, but forms an additional 15 item or "extra". Referring to Figs. 32, 33 and 34 it will be noted that the actuator shaft 49 has rigidly secured thereto a ratchet wheel 278 adapted to be engaged by a spring-pressed pawl 279 pivotally mounted on a 20 push rod 280. This push rod extends transversely to the several shafts and has its one end bifurcated, as indicated at 281, to receive the shaft 83. The front end of the push rod is supported by a link 282 and is 25 provided with a push button 283 which is arranged on the outside of the cabinet enclosing the mechanism. The actuator shaft 49 is rotatable and has mounted thereon and rigidly secured thereto two gears 284 and 30 285. The gear 284 meshes with gears 286 and 287 loosely mounted on the front and rear counter shafts, respectively. These gears 286 and 287 serve to actuate the baggage 35 counting wheels 288 and 289 in the same manner as the cash and other counting 40 wheels are driven from their actuating gears. Likewise, the gear 285 actuates the baggage counters 290 for the ticket. The actuator shaft 49 has mounted thereon, near 45 one end of the frame, a ratchet wheel 312 adapted to be engaged by a spring-pressed pawl 313 mounted on the intermediate shaft 38, which pawl serves as a retaining pawl 50 to hold the actuator shaft and the counters normally against movement.

The records of the several items registered by the respective registering devices may be taken in any suitable manner. Preferably this is done by printing the records 55 on a web or sheet of paper which is fed into position to receive the impression. As has been heretofore described the several printing counters for the trip records, both for the cashier's record and for the ticket, are 60 arranged in alinement and the several records for the cashier's total record are also arranged in alinement, thus providing two lines of type from which the respective records may be printed. Arranged adjacent 65 to the line of type which is in printing po-

sition, and preferably in the rear thereof, are suitable electrotype plates, as shown at 291, in Fig. 5, which have formed thereon a suitable heading for the record, these headings comprising both the proper indications 70 for the several items registered and such other fixed matter as it is desired to print on the ticket. In the present instance this other matter includes the name of the company operating the vehicle and the number 75 of the machine. If desired, suitable date printing mechanism may also be provided and such mechanism is indicated at 292 in Fig. 5. This date printing mechanism is of a well known construction, such as is shown 80 in Patent No. 839,630, granted Dec. 25, 1906, to W. I. Ohmer *et al.*, and forms no part of the present invention and it is, therefore, unnecessary to show or describe the same in detail. The device by means of which the 85 records are taken from the counters and from the electrotype is preferably located in the lower part of the machine and comprises a printing roller 293, shown in Fig. 5 and in detail in Fig. 63. This printing 90 roller is so controlled that the first operation of the printing mechanism, that is, at the beginning of the trip, will cause it to engage the trip printing counters only, while the second operation of the printing mechanism, at the end of the trip, will cause the 95 roller to engage both the type on the printing counters and the electrotype plate, thus printing the heading upon the trip record for the cashier's record and upon the ticket. 100 A suitable inking device is arranged to engage the type to be printed from and in advance of its engagement by the printing roller. The printing roller is preferably supported in a carriage 294 comprising end 105 members arranged adjacent the end members of the main frame and connected one to the other by a tie rod 295. Each of the end members of the carriage is provided along its lower edge with teeth 296 arranged 110 to mesh with pinions 297 rotatably mounted on the adjacent end members of the main frame. These pinions are actuated by a gear 298 rigidly secured to a printing shaft 299 journaled in the end members of the 115 main frame and operated in a manner hereinafter to be described. The inking device is preferably in the form of an inking roller 300 and is supported upon the carriage which carries the printing roller 293 120 and is so arranged that it will engage the type in advance of their engagement by the printing roller. The movement of the roller is controlled by grooved cam plates 301 supported by the respective end members 125 of the main frame. The end members of the carriage 294 are arranged between the printing roller and the cam plates 301 and are provided with vertical slots 302 through which the shaft 304 of the printing 130

roller 293 extends and which permits the roller to move vertically to accommodate itself to the grooves in the cam plates, but prevents any lateral movement of the roller independently of the carriage.

The shaft 304 of the roller is provided in each end with a spring-pressed plunger 305 which plungers extend beyond the sides of the carriage and into the grooves in the respective cam plates. The grooves in the cam plate comprise two substantially parallel grooves of varying depth arranged one above the other, as indicated at 306 and 307. (See Fig. 7.) These parallel grooves are connected one to the other by a series of inclined grooves 308, 309, 310 and 311. The normal or idle position of the printing roller is in the lower longitudinal grooves 307 near the inclined grooves 309. When in this position, the first movement of the driver's printing mechanism will cause the roller to move forward, as indicated by the arrows in Fig. 17, toward the inclined grooves 308. The bottoms of the grooves 307 are inclined from the grooves 309 toward the grooves 308, and, at their point of juncture with those grooves, are of less depth than the grooves 308. When the carriage has reached the forward limit of its movement the plungers of the printing roller shaft will have passed from the grooves 307 into the grooves 308 and the return movement of the carriage will cause them to move up the inclined grooves 308 into the upper longitudinal grooves 306. The forward movement of the carriage will thus move the inking roller into engagement with the type to be printed from and the return movement of the carriage will cause the printing roller to engage these type, or rather to press the paper, on which the record is to be printed, into engagement with the type. At the end of the first printing operation the printing roller will remain at rest in the upper grooves 306, as indicated in Fig. 17. Upon the next operation of the driver's printing mechanism the carriage will be again moved forward and the plunger for the printing roller caused to travel down the inclined grooves 309 and forward through the grooves 307 into the grooves 308, thence upwardly and rearwardly as before. The rearward movement imparted to the carriage by the second operation of the printing mechanism is greater than the rearward movement imparted by the first operation of the printing mechanism and the roller will be carried past the grooves 309 to the upper ends of the grooves 310, thus carrying the printing roller into operative engagement with both the type on the counter wheels and with the electrotype plates and printing the trip records and the headings for said records. The completion of this second operation will cause the roller to move down-

ward along the grooves 310 into the grooves 307 and to its normal position at the bases of the grooves 309. It is to be noted that the bottoms of the grooves 306 and 307 comprise a series of inclines, each incline beginning at one of the inclined grooves and terminating at the next succeeding inclined groove in the direction of movement of the feed roller. Consequently, when the roller has been moved from one groove to the other the spring-pressed plunger will pass over the shoulder formed at the juncture of the inclined groove with the longitudinal groove and will be prevented from moving back along the longitudinal groove. When the printing mechanism is operated by the cashier to take the total record at the end of the day the carriage 294 is moved rearward from its normal position. This rearward movement of the carriage causes the plungers of the roller shaft to travel rearward along the lower grooves 307 and upward through the grooves 311 into the upper grooves 306. This movement of the carriage causes the inking roller to pass over the type to be printed from while the printing roller is maintained out of engagement with the type. The forward movement of the carriage now causes the ends of the shaft to move forward along the upper grooves 306, thereby carrying the inking roller across the freshly inked type and causing the paper which extends between the rollers and the type to receive an impression from the latter. When the rollers reach the upper ends of the grooves 310 they move downward through these grooves into the lower grooves and forward to their normal positions. It will, of course, be understood, that when in its normal position the printing roller is so located that the ends of the spring-pressed plungers will not pass beyond the shoulders at the juncture of the longitudinal grooves 307 and inclined grooves 309, but will rest on the edges of the shoulders, thus permitting the roller to be moved in either direction.

The devices by means of which the driver operates the printing mechanism may be of any suitable character. In the present instance they are such that the movement of a handle through half a revolution at the beginning of the trip will print the zero record and that a second movement of the same handle through a half revolution at the end of a trip will print the trip records and headings. The operating mechanism, by means of which the cashier's record is printed, is entirely separate from that by which the trip record is printed. In the construction here shown the printing shaft 299 has rigidly secured thereto on the outside of the end member 1 of the main frame a pinion 314, Figs. 6, 11, 24, 25 and 26, which meshes with a toothed segment 315 which meshes with a toothed segment 315

carried by an arm 316 pivotally supported by the end member of the frame, as shown at 317. A pitman 318 is pivotally connected to the arm 316 at a point between its pivotal connection to the main frame and the toothed segment and this pitman is so connected to the operating handle that a half revolution of this handle will impart to the segment the movement necessary to give the carriage the required amount of movement in the desired direction. In the form of mechanism herein shown this pitman is actuated by a cam 319 loosely mounted upon a stud shaft 320 rigidly secured to the end member of the frame, Fig. 24. This printing cam comprises a plate having in one face thereof a cam groove into which extends a pin 321 carried by the pitman 318. This pin is arranged some distance from the upper end of the pitman, which has its upper end bifurcated, as indicated at 322. The arms of the bifurcated portion of the pitman extend on the opposite sides of the shaft 320 and form guides to retain the pitman against lateral movement. The printing cam 319 has rigidly secured thereto a two toothed disk 323, Figs. 25 and 26, the teeth of which are spaced equidistant about its circumference. This disk is actuated by a pawl 324 which is carried by a plate 325 loosely mounted on the shaft 320 and having a hub 326 by means of which it is connected with the hub of the handle 327 which is rotatably mounted upon a bearing screw 328 mounted in the end of the stud shaft 320. The connection between the hubs of the handle and the plate is, in the present instance, formed by providing these parts with interlocking projections and notches. The pawl 324 has a heel portion 329 arranged to engage a stop 330, Fig. 15, carried by the main frame and so arranged as to engage the pawl and bring the plate and the handle to a standstill when the handle has moved through a half revolution. The stop preferably has its forward edge beveled so that the heel 329 will ride over the same, thus forcing the pawl into the notch at the base of the tooth on the disk 323, and prevent the disk and the printing cam from running past the pawl. In this manner it will be apparent that the movement of the lever from its normal or upper position through a half revolution will cause the printing cam to move through a half revolution. The corresponding portion of the groove in the printing cam is so shaped that the pitman will impart the desired movement to the printing shaft and the carriage. Upon the return of the handle to its normal position the pawl will ride over the toothed disk and the position of the printing cam will not be affected. Figs. 24 and 26. Upon the next downward movement of the handle, at the end of a trip, the cam will

be rotated through the second half of its revolution. The groove in the corresponding portion of the cam is so shaped that the printing roller will be carried through the longer movement, above described, thus 70 printing from the headings, as well as from the counters. Suitable mechanism is provided to force the operator to move the handle through a complete half revolution in one direction before it can be moved in 75 the other direction. As here shown this mechanism consists of an arrester of a well known type comprising a toothed segment 533, Fig. 6, secured to the edge of the plate 325 and a spring held pawl 534 mounted on 80 the cabinet and arranged to be engaged by the segment 533 when the printing handle is actuated.

The signal or flag is locked against movement, either from its normal position or 85 from its "engaged" position until the printing mechanism has been operated. To so lock the flag the arm 164, which is rigidly secured to the flag, is in the form of a segmental plate Figs. 6, 15, 18 and 26, having 90 in its lower portion a recess forming a shoulder 331 adapted to engage the nose of a pawl 332 which is pivotally mounted upon a stud 333 carried by the end member of the main frame and is held normally in position to be engaged by the arm 164 by a spring 334 connected at one end to a finger 335 rigidly secured to the pawl 332 and at its other end to a fixed part of the main frame. The pawl is moved out of the path 100 of the arm 164, against the tension of the spring 334, by means of a pitman 336 which is operated by the printing mechanism. This pitman is provided at one end with an elongated slot 337 adapted to receive a pin 105 338 carried by an arm 339 rigidly connected with the pawl 332. The opposite end of the pitman is connected to the plate 325, which is rigidly connected with the printing handle 327. The end of the pitman 110 is preferably curved and is so connected to the plate 325 that when the handle is in its normal position the point of connection of the pitman with the plate will be in substantially the same horizontal plane with 115 the axis of the handle. The length of the slot 337 is such that the pin 338 will not be operatively engaged by the pitman and the pawl moved against the tension of the spring until the last portion of the stroke 120 of the handle, when a sufficient movement will be imparted to the pawl to move it out of the path of the arm 164. The pawl 332 is retained in its outer or inoperative position by means of a finger or detent 341 pivotally mounted on the main frame, preferably on the shaft 167 and having a notch 125 in its outer end adapted to be engaged by a lateral projection 342 carried by the arm 339 which is, in the present instance, formed 130

integral with the pawl 332. A spring 343 is connected at one end to the detent 341 and at the other end to the main frame at a point substantially in alignment with the shaft 167 and the projection 342. Consequently, the tendency of the spring is to move the detent 341 into alignment with the shaft 167 and the projection 342, in which position the projection will enter the notch 345 and the pawl 332 will be held in its inoperative position. When the pawl is in its operative position, in the path of the arm 164 the projection 342 will extend above the upper edge of the detent 341, as shown in Figs. 6 and 18. When the printing mechanism is operated and the pawl moved into its inoperative position the projection 342 will be carried out of engagement with the detent 341 and the spring will move the finger into alignment with the shaft and the projection. Thus, when the printing handle has been returned to its normal position and the pitman 336 no longer holds the pawl against movement the projection will engage the notched end of the detent 341 and prevent the return of the pawl to its normal position. A finger 344 is rigidly secured to the detent 341 and extends into the path of the pin 165 carried by the arm 164. Consequently, when the flag is moved into its lower or "engaged" position the pin 165 will engage the finger 344 and move the detent 341 out of the path of the projection 342, thus permitting the spring to move the pawl inwardly toward its normal position. By the time the pin 165 has engaged the finger 344 the edge of the finger 164 will have passed the nose of the pawl, and, when the pawl is released, it will ride over the edge of the arm 164 until the arm as a whole has passed the nose of the pawl, when the nose of the pawl will be moved over and will engage the upper corner of the arm and will thus lock the arm and the flag in their lowermost positions, as shown in Fig. 18. When the parts are in this position the lower edge of the detent 341 will rest upon the projection 342, and the flag will be retained against movement until the printing mechanism has been again operated, to print the trip record. Upon the operation of the printing mechanism the pawl is moved into its inoperative position and retained in that position by the detent as before. Upon the completion of the printing operation the flag is returned to its normal position and the pin 165 again engages the finger 344 and moves the detent 341 out of the path of the projection 342, thereby permitting the pawl 332 to be again moved into its operative position beneath the arm 164.

It is essential to the proper operation of this locking pawl that the printing handle should be returned to its normal position to withdraw the pitman and leave the pawl

free to operate under the tension of its spring. Means are, therefore, provided for further locking the flag against movement when the printing handle is out of its normal position. This is, in the present instance, accomplished by two coöperating plates, one rigidly connected to the handle 327 and the other to the flag 159, as more clearly shown in Fig. 24. As here shown the plate connected to the handle is the plate 325 carrying the pawl 324, while the plate connected to the flag is a special plate, indicated at 340. The plate 325 has formed in one side thereof a segmental recess, as indicated at 345, this recess being formed on a radius corresponding substantially to the radius of the plate 340 and being so arranged in the plate 325 that when the handle is in its normal or uppermost position the notch 345 will lie adjacent the plate 340. The plate 340, in turn, is provided with two notches, as indicated at 346 and 347, both formed on a radius substantially equal to the radius of the plate 325 and so arranged in the plate 340 that, when the flag is in its normal position, the notch 346 will be adjacent to the plate 325, and, when the flag is in its "engaged" position, the notch 347 will be adjacent to the plate 325. With this arrangement of the notches it will be apparent that when both the handle and the flag are in their normal positions the notches 345 of the plate 325 and the notch 346 of the plate 340 will lie adjacent one to the other, and either plate can be rotated. As soon, however, as one plate has begun to rotate a portion of that plate will enter the notch on the other plate, thus preventing the movement of the second plate. It, therefore, becomes apparent that when the flag is in either its normal or its "engaged" position it cannot be moved from that position until the printing handle has been returned to its normal or uppermost position, and further, it will be apparent that the printing mechanism will be locked against movement during the movement of the flag and can be operated only when the flag is in either its "engaged" or "for hire" position.

The cashier preferably operates the printing mechanism by means of a socket wrench or key which fits over the squared end of the printing shaft at the left hand end of the machine, as shown at 348 in Figs. 8 and 9. It is desirable, first, that the cashier should not be able to operate the printing mechanism for the trip counters, and, second, that the printing mechanism should be in its normal position before he can operate the same to print from the total counters. To this end the opening formed in the cabinet 163 to permit the key 348 to engage the squared end of the printing shaft is provided with an offset portion or recess 349 and the key is provided with a correspond-

ing projection 350 which is so arranged on the key that the key can be inserted in the opening only when the projection is in alignment with the recess, and, when the key is in proper engagement with the end of the shaft, the projection will lie wholly within the cabinet, thus permitting the key and the shaft to be rotated. A stop 351 is rigidly secured to the cabinet at one side of the recess 350 and prevents the key and the printing shaft from being turned in that direction and makes it possible for the cashier to turn the shaft only in a direction to print from the total counters, and further, this stop makes it necessary for the cashier to return the printing mechanism to its normal position before he can withdraw his key. The printing cam 319 for the trip records is provided with a vertical slot 321^a so arranged that, when the printing cam is in its normal position, the slot will be in alignment with the pin 321 carried by the pitman 318, thereby permitting the movement of the segment 315 when the printing shaft 299 is actuated by the cashier. It will be noted that the grooves in the cam plate 319 co-operate to prevent the operation of the printing mechanism by means of one operating device before the other operating device has been returned to its normal position. If the driver has not returned his operating handle for the printing mechanism to its normal position the groove 321^a will be out of alignment with the pin 321 and the segment 315 will be locked against movement by the rotation of the printing shaft, and, consequently, the cashier will be unable to print a record. If the cashier does not return the printing mechanism to its normal position the pin 321 will lie within or partially within the groove 321^a and the cam 319 will be locked against rotation, thus preventing the driver from operating the printing mechanism.

45 The paper upon which the records are printed is arranged in suitable rolls 352 and 353 supported by the main frame in the rear part of the machine, as shown in Fig. 2. The web or roll 353, which is to receive the cashier's record, is of greater width than the web or roll 352 from which the tickets are to be formed. Inasmuch as the ticket is cut off and removed after each trip it is necessary to feed a greater length of paper for the ticket than is required for the cashier's record. Consequently, separate feeding devices are provided for the two rolls of paper. Referring first to the feeding mechanism for the ticket, the paper is carried from the roller 352 under a shield 354, Fig. 5, extending about the inking roller 300, over the printing roller 298 and between feeding rollers 355 and 356, thence to suitable cutting mechanism, by means of which the ticket is severed. The feeding rollers 355 and 356

may be operated in any suitable manner to advance the paper a sufficient distance prior to each printing operation. In the present instance this feeding mechanism is controlled by the printing handle which, as above stated, has two movements for each printing operation, and the rolls are actuated from a cam which is so shaped that the first movement of the printing handle to print the zero record will not affect the rollers or the paper, but at the beginning of the second movement of the printing handle the rollers will be operated to feed the paper forward a distance sufficient to space the zero and trip records a proper distance apart. During that portion of the stroke of the handle when the actual printing is being accomplished the rollers are stationary. After the completion of the actual printing and while the printing roller is being returned to its normal position the feeding rollers are operated to feed the paper forward and space the records apart. When the printing mechanism is operated to print the trip record the action of the feeding mechanism is the same except the movement of the rollers is such as to feed the paper forward a distance sufficient to carry the record just printed beyond the cutting mechanism so that the operation of this mechanism will sever that portion of the paper which carries the record. This long second feeding operation of the rollers carries the record just beyond the cutting device and thus places it at the top of the ticket, and further, this long movement of the rollers carries forward a portion of the paper sufficient to provide the next ticket issued with a body large enough to enable it to be conveniently handled. The ticket feeding cam is preferably in the form of a circular plate, as indicated at 357, Figs. 15 and 16, having a cam groove, mounted upon the shaft 320 and rigidly connected with the printing cam 319. This groove is adapted to receive a pin 358 carried by a pitman 359 having one end bifurcated, as shown at 360, and adapted to ride upon the shaft 320 and cause the pitman to move in a right line toward and away from said shaft. The opposite end of the pitman 359 is provided with a rack 361 adapted to mesh with a pinion 362 mounted upon a stud shaft 333. The pitman is preferably provided with a depending portion 363 having a slot 364 extending about the shaft 333 and serving both to guide the adjacent end of the pitman and maintain the rack 361 in mesh with its pinion. A segment 365 is also mounted on the stud shaft 333 and is rigidly secured to the pinion 362. This segment meshes with a pinion 366 mounted on a stud shaft 367 carried by the end member of the main frame and having rigidly secured thereto a segment 368 also mounted on the stud shaft 367. The segment 130

368 meshes with a pinion 369 loosely mounted upon the shaft, 370, of the upper feed roller for the ticket feed. This pinion 369 has rigidly secured thereto an arm 371 having a spring-pressed pawl 372 arranged to engage a one-tooth ratchet wheel 373 which is rigidly secured to the shaft of the upper roller 355. A gear 374 is rigidly secured to the shaft of the upper roller and meshes with a gear 375 rigidly secured to the shaft of the lower roller 356, thus causing the two rollers to rotate in unison in opposite directions. In this manner it will be apparent that the reciprocation of the pitman under the influence of the cam plate 357 will rotate the two ticket feeding rollers in a forward direction only, the pawl and ratchet wheel connection between the pinion 369 and the shaft of the upper roller permitting the rearward movement of the pitman to take place without affecting the positions of the feeding rollers. A retaining pawl 420 is mounted on the end member of the main frame and engages a ratchet wheel 421 to prevent the rollers from turning rearwardly. If desired, one or both of the ticket feeding rollers may be provided with electrotypes to print an advertisement upon the ticket. In the present instance the lower roller 356 is shown as provided with an electrotype 376. In order that the advertisement may be properly placed on the back of the ticket the train of operating gearing is of such a ratio that the combined length of the two feeding movements of the rollers will equal the length of the ticket, the circumference of the roller being equal to the length of the ticket. The shafts for the feeding rollers 355 and 356 are mounted at one end in the adjacent end member of the main frame and at the other end are supported in suitable bearings carried by an auxiliary frame 377 which is supported upon tie rods 378.

Suitable means are provided for severing that portion of the web of paper which lies beyond the feed rollers at the end of the second movement thereof and which bears the record. This mechanism preferably comprises a fixed member 379 extending longitudinally to the feed rollers and having a longitudinal recess in which is slidably mounted a cutter bar 380. Springs 381 are arranged in the recess in the fixed member in the rear of the cutter bar and tend to move the same outward. The movable member, as shown in Figs. 5 and 64, comprises a longitudinal bar 382 supported at its opposite ends by arms 383. The arm 383 adjacent the end member of the main frame is rotatably mounted upon the shaft of the upper feed roller, while the arm 383 at the opposite end of the bar 382 is journaled upon a bearing 384 in which the adjacent end of the shaft of the upper feed roller is journaled. The bar 382 is provided in its lower edge with an

elongated recess 385, the base of which forms a cutting edge for the bar. Those portions of the bar 382 at the opposite ends of the recess will obviously extend some distance below the cutting edge of the bar and will form supports against which the cutter bar 380 bears and will prevent the springs 381 from forcing said cutter bar out of the recess, the movement of the bar 382 being such that the lower edge thereof is never carried beyond the cutter bar 380. The outer face of the bar 382 is curved to conform to the arc of a circle, about the axis of which it moves. Consequently, the cutter bar 380 will be maintained at all times in proper relation to the movable cutting member 382 and the web of paper which extends through the elongated slot 385 of the cutting member 382 will be maintained at all times in its proper relation both to the cutting members and to the electrotype on the feed roller. The movement of the movable cutting member 382 is so timed that it will take place just at the end of the second feeding movement of the feeding roller. To this end a crank arm 386 is rigidly connected with that arm 383 adjacent the end member of the main frame and a pitman 387 is pivotally connected at one end to the crank arm 386. This pitman is preferably actuated by means of a cam controlled by the movement of the printing handle. In the present instance this cam comprises a groove formed in that side of the plate 357, constituting the printing cam, opposite the cam groove which actuates the pitman for the feeding roller, as shown at 388 in Fig. 16. The pitman 387 has a pin 389 arranged to fit within the groove 388 and also has its end bifurcated, as indicated at 390, and extending about the shaft 320 to guide the pitman in a right line toward and from the shaft. The groove 388 is so shaped that the first movement of the printing handle will not affect the pitman or the cutting mechanism and the pitman will only be actuated during the last portion of the second movement of this handle and after the movement of the feeding rollers has been completed.

The feeding rollers 391 and 392 for the cashier's record are arranged in alinement with the feeding rollers for the ticket, and, as here shown, have those ends adjacent to the ticket feeding rollers supported in the same bearings, carried by the auxiliary frame 377, in which the inner ends of the shafts for the ticket feeding rollers are journaled. The opposite ends of the cashier's record feeding rollers are journaled in the end member of the main frame. These rollers may be of any suitable character, but, as indicated in Fig. 45, they each comprise two sections arranged to engage the web of paper near its opposite edges and to leave the central portion of the web

free. Owing to the different distances which the paper for the two records is fed it is necessary that the feeding mechanism should be separate, and, consequently, the feeding mechanism for the cashier's record feeding rollers is arranged on the opposite end of the machine from the feeding mechanism for the ticket feeding rollers. (See Figs. 8 and 9). This mechanism comprises a cam plate 393 rigidly secured to the printing shaft and having a cam groove adapted to receive a pin 394 carried by a pitman 395. The pitman has one end bifurcated, as indicated at 396, and engaging the printing shaft to guide the pitman. The opposite end of the pitman is provided with a rack 397 arranged to mesh with a pinion 398 mounted upon a stud shaft 399 carried by the adjacent end member of the main frame. The pitman also preferably has a slotted plate 400 extending about the stud 399, adapted to retain the rack 397 in mesh with the pinion and to act as a guide for the adjacent end of the pitman. A gear 401 is rigidly secured to the pinion 398 and meshes with a second gear 402 having rigidly secured thereto an arm 403 carrying a pawl 405 which meshes with a ratchet wheel 406 rigidly secured to the shaft 407 of the upper feeding roller. This shaft has rigidly secured thereto, preferably on the inner side of the frame member, a gear 408 which meshes with a similar gear 409 rigidly secured to the shaft 410 of the lower feeding roller. A spring-pressed retaining pawl 411 is mounted on the inner side of the end member of the main frame and meshes with a ratchet wheel 412 to lock the rollers against reverse movement when the pitman and the rack 397 are moved rearwardly. In the present machine no positively operated cutting mechanism for the cashier's record is provided, but a plate 430 is mounted on the main frame in front of the upper feed roller, and, when the total record has been printed, the end of the sheet is grasped by the cashier and drawn outward until the total record has passed beyond the feeding roller and the sheet is then torn off along the edge of the plate 430.

The rockshaft 33 on which the alining pawls for the cash counters and the mileage counters are mounted, is also actuated by the movement of the printing shaft to cause these pawls to engage their respective ratchet wheels and aline their respective counters prior to the beginning of the actual printing operation. To this end the cam plate 393 is provided in one edge with a recess 413 so arranged that when the printing shaft is in its normal position the recess will be in a position to receive a projection or stud 414 carried by a lever 415 pivotally mounted between its ends on the main frame of the machine. The opposite end of the

lever 415 is pivotally connected to one end of a pitman 416, the opposite end of which is connected to a crank arm 417 rigidly secured to the rockshaft 33. When the printing mechanism is in its normal position the rockshaft will be maintained in such a position as to support the pawls out of engagement with their respective ratchets. The first portion of the movement of the printing shaft will carry the recess 413 beyond the stud 414 of the lever 415, causing the stud to ride over the periphery of the cam plate, rocking the shaft 33 about its longitudinal axis, bringing the pawls into engagement with their ratchet wheels and retaining the same in engagement therewith during the printing operation, thereby alining the printing counters and retaining the same in their alined positions until the records have been printed. It will be noted that this operation of the alining pawls will be the same in whichever direction the printing shaft is moved, and, consequently, the counters will be alined both for the trip records and for the total records.

When the ticket is severed from the web of paper upon which the record has been printed it is discharged from the machine through a suitable opening, and, if desired, means may be provided for delivering this ticket to the passenger within the vehicle, it being understood that the machine itself is usually supported at one end of the driver's seat in front of the front partition of the vehicle and in such a position that the visual indicator is visible both to the passenger in the vehicle and to the driver. One form of device for so delivering the ticket is shown in Fig. 62 of the drawings and comprises a conveyer, such as a chute 418, which extends from the machine through the front partition of the vehicle and is so inclined that the ticket, when severed and dropped into the chute, will slide of its own accord to the lower end of the chute where it will be retained by means of a suitable stop 419 until removed by the passenger. It will, of course, be obvious that this same result could be accomplished in many other ways. Further, it will be apparent that the character of the ticket issued may be greatly varied and that the items printed upon this ticket may be such as seem desirable in connection with the particular service in which the machine is employed. In the preferred form, which the machine above described is adapted to print, the fare is the principal item given, and, in addition to this, the number of pieces of baggage carried and the number of the trip are given, together with the heading. In Fig. 69 of the drawings there is shown a modified form of ticket in which the items are the same as those given in the cashier's record.

The operation of the several parts of the machine will be readily understood from the foregoing descriptions thereof and it will be apparent that when the machine is 5 "for hire," as when standing at a cabstand, the flag will be in its normal or raised position and will indicate that the vehicle is for hire, the trip mileage registering devices and the fare registering devices, both 10 trip and total, will be disconnected from their respective driving mechanisms, and the time registering devices will be permanently connected with the clock and will register the time of day regardless of whether 15 the machine is "for hire" or is "engaged." When a passenger appears and the vehicle is engaged the driver first moves his printing handle through a half revolution and back to its normal position, thereby printing 20 the zero record, or a record of the condition of the several registering devices at the beginning of the trip. The zero record should show the number of the trip, the time of day at which the vehicle is engaged and the 25 driver's number. The trip baggage registering devices, the trip fare registering devices and the trip mileage registering devices should print zero records. After the 30 operation of the printing handle the driver moves his flag into its lower or "engaged" position, thereby advancing the trip fare registering devices, both for the ticket and for the cashier's record, to the amount of the minimum fare, adding this amount to 35 the total fare registering devices and also connecting the fare registering devices and the trip mileage registering devices with their respective actuating mechanisms. As 40 has been explained the fare registering devices will not be further actuated after registering the minimum fare until the actual fare, based upon the time consumed or the distance traveled, equals the amount of the minimum fare. The fare registering devices 45 will then be actuated from the wheels of the vehicle so long as the vehicle is moving above a predetermined minimum speed. When the vehicle is moving at a speed lower than the predetermined minimum speed or 50 is at a standstill, the fare registering devices will be actuated by the clock mechanism. As a result the fare computed is based upon a combination of the time and the distance. At the beginning of the trip the 55 driver should also actuate the baggage registering devices to register the number of pieces of baggage carried. At the end of the trip when the passenger is discharged the driver again moves his printing handle 60 through a half revolution and back to normal position, thereby printing the trip records and heading. The trip records should show the number of the trip, the number of pieces of baggage carried, the time at which 65 the passenger was discharged, the amount of the fare, based upon both time and distance, the distance traveled and the number of the driver, while the heading, which is printed at the same time as the trip record, will show the date on which the trip was made, together with the machine number. The 70 movement of the printing handle also severs and delivers the ticket, on which is printed the amount of the fare, number of pieces of baggage and the number of the trip. The 75 amount of fare due at the end of the trip, as well as at all stages of the trip, is indicated by the visual indicator and the fare so indicated at the end of the trip should correspond to the fare printed on the ticket. After 80 the completion of the printing operation the driver returns his flag to its normal or "for hire" position, thereby disconnecting the trip mileage counters and the fare registering devices, both trip and total, from their 85 respective actuating mechanisms, and, at the same time, resetting the baggage registering devices, trip fare registering devices and trip mileage registering devices to zero and further restoring the actuating cam for the trip 90 mileage registering devices to zero position. As has been stated the time registering devices are never disconnected from the clock and are never reset. Consequently, the 95 amount of time consumed by the trip is computed by finding the difference between the time of starting and the time of discharging the passenger, but it will be obvious that by resetting the time registering devices to zero at the beginning of each trip the actual 100 time consumed by that trip will be registered. The total mileage differs from the total fare in that instead of being a record for the day or a predetermined time only it is a grand total record of the distance traveled by the vehicle either from the time the taximeter was installed upon the same or from some other fixed prior date, such for example as when the vehicle was equipped 105 with new tires, it being customary to pay by the mile for tires used on vehicles of this kind. It will also be noted that owing to the clutch connection between the driving wheel or worm wheel and the registering devices, any rearward movement on the part 110 of the vehicle will not affect these devices. Should the vehicle be delayed for any cause which could not be fairly charged to the passenger, such for example as a break down of the driving mechanism or a puncture of a tire, this delay can readily be taken care of by printing a record at the beginning of the delay and issuing a ticket to the passenger and then, when the trouble has been 115 remedied and the trip resumed, printing another zero record and at the end of the trip printing a second trip record and issuing a second ticket to the passenger, the passenger being required to pay the amount 120 of both tickets when he leaves the vehicle. 130

While the present machine is not designed to indicate the number of passengers carried it will readily be apparent that the baggage registering devices can be utilized for this purpose by a mere change of the heading, or that a similar device could be provided to indicate the number of passengers. It will also be obvious that additional registering devices could be added to the machine to register other items that might be desirable under particular circumstances, such, for instance, as the "waiting time" or the time when the vehicle is not in motion but is in the employ of a passenger.

The record kept by this machine enables the company operating the vehicle to keep in close touch with the movements of the vehicle, the amount of business done and the distance traveled thereby. The total distance traveled for each day can be readily secured by comparing the present day's record with the preceding day's record. Having the several trip records showing the live mileage, that is, the number of miles traveled with a passenger, it can be readily ascertained whether the ratio between the live miles and the total number of miles traveled is a proper one. The total cash record, together with the total number of pieces of baggage, indicates the amount of cash which should be turned over by the driver, and a comparison of the time the vehicle is in actual service, or the live time, with the total time for the day will indicate whether or not a proper ratio exists between these records. Each record identifies the driver who made it, as the number of the key by means of which the machine was unlocked is printed on each record and each driver is provided with a key bearing his own particular number. Likewise, the record bears the number of the machine by which it was made, thus affording a double identification. The ticket bears both the machine number and the trip number, thus enabling the cashier's record corresponding to each ticket to be identified in case a passenger should desire to make a complaint or for any other reason should desire to check the ticket against the record. The system of locks for the machine is such as to effectually prevent the driver making false records. He must print his zero record before it is possible to move his flag into "engaged" position and the movement of the flag into "engaged" position connects the several registering devices with their driving mechanisms. Further, he is obliged to print his trip record before he can return his flag to its "for hire" position, and, consequently, the actual distance and fare must necessarily be registered.

As has been heretofore stated the present machine is shown and described for the purpose of illustration only and it will be ob-

vious that many, if not all, of the several detail parts of the machine, as well as the machine as a whole, can be greatly varied without departing from the spirit of the invention and it will be understood that the invention is not to be limited to the details of construction shown and described, for obvious modifications will occur to a person skilled in the art.

Having thus fully described our invention, what we claim as new and desire to secure by Letters Patent, is:—

1. The combination, with a wheeled vehicle, of two sets of trip registering devices, each set including devices to register a fare, separate actuating devices for each set of registering devices, single means for connecting both of said actuating devices with one of the wheels of the vehicle, and means for printing a ticket containing the items registered by one of said trip registering devices and for printing a record of the items registered by the other of said trip registering devices.

2. The combination, with a wheeled vehicle, of two sets of trip registering devices, each set including devices to register a fare, separate devices for simultaneously actuating said fare registering devices from one of the wheels of said vehicle, and mechanism for taking a record from one of said fare registering devices and issuing it as a ticket and for taking a record from the other of said registering devices and retaining said last-mentioned record within the machine.

3. In a machine of the character described, the combination, with a vehicle, of two sets of trip registering devices, one set including devices to register a plurality of items relating to each trip and the second set including devices to register a part only of the items registered by the first set, means to actuate said registering devices from a moving part of said vehicle, and means to print a record from each set of said registering devices.

4. In a machine of the character described, the combination, with mechanism for registering the distance traveled, mechanism for registering the time, and mechanism for computing the fare from the distance and the time so registered and for registering said fare, of separate devices for printing and issuing a ticket showing the amount of said fare and for printing a record of the several items so registered.

5. In a machine of the character described, the combination, with mechanism for registering the distance traveled, mechanism for registering the time and mechanism for computing the fare from the distance and the time so registered and for registering said fare, of separate devices for printing and issuing a ticket showing the amount of said fare and for printing a record of the

several items so registered, and a single operating mechanism to cause the operation of said separate devices.

6. The combination, with a vehicle, of a shaft, a counting device mounted on said shaft and comprising a counting member and a gear connected therewith, a second shaft extending parallel to the first-mentioned shaft, a driving gear mounted on said 10 second shaft and connected with said counter gear, a ratchet wheel connected with said driving gear, a pawl arranged to engage said ratchet wheel, a third shaft also extending parallel with the first shaft, and 15 mechanism mounted on said third shaft and controlled by the movement of said vehicle for actuating said pawl.

7. In a machine of the character described, the combination, with a vehicle, of a shaft, a counting device mounted on said shaft and comprising a counting member and a gear connected therewith, a second shaft extending parallel to the first shaft, a driving gear mounted on the second shaft 25 and connected with said counter gear, a ratchet wheel operatively connected with said driving gear, a lever mounted on said second shaft, a pawl carried by said lever and adapted to engage said ratchet wheel, 30 a third shaft also extending parallel to the first shaft, a cam mounted on said third shaft and arranged to engage said lever, and means actuated from a moving part of said vehicle to rotate said cam.

8. In a machine of the character described, the combination, with a counting device, and means for actuating the same, of a shaft, a cam mounted on said shaft and arranged to impart movement to said actuating means, means for rotating said cam on said shaft, and means for causing said cam to rotate with said shaft.

9. In a machine of the character described, the combination, with a counting device, an actuator therefor comprising a ratchet wheel, a pawl arranged to engage said ratchet wheel, and a lever carrying said pawl, of a shaft, a cam mounted on said shaft to actuate said lever, means for rotating said cam on said shaft, and means for causing said cam to rotate with said shaft.

10. In a machine of the character described, the combination, with a counting device, and means for actuating the same, of a shaft, a cam rotatably mounted on said shaft and arranged to impart movement to said actuating means, means for rotating said cam, a pawl connected with said cam, and a toothed disk rigidly secured to said shaft, whereby said cam may be caused to rotate with said shaft when the latter is turned in one direction.

11. The combination, with a vehicle, a counting device, a pinion connected therewith, means controlled by the movement of

said vehicle for actuating said counting device, and a pinion connected with said actuating means, of a gear meshing with both of said pinions, and means for operating said gear to reset said counting device to zero and return said actuating means to its initial position.

12. The combination, with a vehicle, a counting device comprising a resetting shaft, a counter rotatably mounted thereon, a second shaft, a device rotatably mounted on said second shaft and controlled by the movement of said vehicle to actuate said counters, and means to cause said actuating device to rotate with said shaft, of means for rotating said shafts to return said counters and said actuating means to their zero positions.

13. The combination, with a vehicle, a counting device, a ratchet wheel operatively connected with said counting device, a pawl arranged to engage said ratchet wheel, a lever carrying said pawl, a shaft, a cam loosely mounted on said shaft and arranged to impart movement to said lever, means controlled by the movement of said vehicle for rotating said cam on said shaft and thereby actuating said counting device, and means to cause said cam to rotate with said shaft, of means for resetting said counting device to zero and for rotating said shaft to return said cam to its initial position.

14. The combination, with a vehicle, a counting device, a ratchet wheel operatively connected with said counting device, a pawl arranged to engage said ratchet wheel, a lever carrying said pawl, a shaft, a cam loosely mounted on said shaft and arranged to impart movement to said lever, means controlled by the movement of said vehicle for rotating said cam on said shaft, and means to cause said cam to rotate with said shaft, of means for resetting said counting device to zero and for rotating said shaft to return said cam to its initial position, and means for rendering said pawl inoperative while said cam is being returned to its initial position.

15. In a machine of the character described, the combination, with a counting device, of a shaft, a ratchet wheel mounted on said shaft and operatively connected with said counting device, a lever mounted on said shaft, a pawl carried by said lever and adapted to engage said ratchet wheel, a second shaft, a cam loosely mounted on said second shaft and arranged to actuate said lever, means for rotating said cam upon said second shaft, and other means controlled by the rotation of said second shaft for rotating said cam.

16. In a machine of the character described, the combination, with a counting device, of a shaft, a ratchet wheel mounted on said shaft and operatively connected with

said counting device, a lever mounted on said shaft, a pawl carried by said lever and adapted to engage said ratchet wheel, a second shaft, a cam loosely mounted on said 5 second shaft and arranged to actuate said lever, means for rotating said cam upon said second shaft, and a pawl and ratchet wheel for connecting said cam to said second shaft, whereby the rotation of said second shaft 10 will rotate said cam.

17. In a machine of the character described, the combination, with a counting device, of a shaft, a ratchet wheel mounted on said shaft and operatively connected with 15 said counting device, a lever mounted on said shaft, a pawl carried by said lever and adapted to engage said ratchet wheel, a second shaft, a cam loosely mounted on said second shaft and arranged to actuate said 20 lever, means for rotating said cam upon said second shaft, other means controlled by the rotation of said second shaft for rotating said cam, and means for rendering said pawl 25 inoperative when said cam is rotated by said shaft.

18. The combination, with a vehicle, of a registering device, a shaft, a ratchet wheel mounted on said shaft and operatively connected with said registering device, a lever 30 mounted on said shaft, a pawl carried by said lever and arranged to engage said ratchet wheel, a second shaft, a cam mounted on said second shaft and arranged to actuate said lever, means controlled by the movement 35 of said vehicle for rotating said cam, and other means for rotating said cam independently of the movement of said vehicle.

19. The combination, with a vehicle, a 40 registering device, a ratchet wheel operatively connected to said registering device, a lever, and a pawl carried by said lever to engage said ratchet wheel, of a shaft, a cam rotatably mounted on said shaft and arranged to actuate said lever, means controlled by the movement of said vehicle for 45 rotating said cam on said shaft, and means controlled by the rotation of said shaft for rotating said cam.

50 20. The combination, with a vehicle, a registering device, a ratchet wheel operatively connected to said registering device, a lever, and a pawl carried by said lever to engage said ratchet wheel, of a shaft, a cam 55 rotatably mounted on said shaft and arranged to actuate said lever, means controlled by the movement of said vehicle for rotating said cam on said shaft, a ratchet wheel rigidly secured to said shaft and rotatable therewith, and a pawl connected with said cam and arranged to be engaged by said ratchet.

60 21. The combination, with a vehicle, a registering device, a ratchet wheel opera-

tively connected to said registering device, a lever, and a pawl carried by said lever to engage said ratchet wheel, of a shaft, a cam rotatably mounted on said shaft and arranged to actuate said lever, means controlled by the movement of said vehicle for 70 rotating said cam on said shaft, means controlled by the rotation of said shaft for rotating said cam, and other means controlled by the rotation of said shaft for rendering said pawl inoperative.

75 22. The combination, with a vehicle, a registering device, a ratchet wheel operatively connected to said registering device, a lever, and a pawl carried by said lever to engage said ratchet wheel, of a shaft, a cam 80 rotatably mounted on said shaft and arranged to actuate said lever, means controlled by the movement of said vehicle for rotating said cam on said shaft, means controlled by the rotation of said shaft for 85 rotating said cam, an arm supported normally out of the path of said pawl, and a connection between said arm and said shaft, whereby the rotation of said shaft will cause said arm to move said pawl into an inoperative 90 position.

23. In a machine of the character described, the combination, with a registering device, a ratchet wheel operatively connected therewith, a lever, and a pawl carried by 95 said lever to engage said ratchet wheel and having a projection, of a shaft, a cam rotatably mounted on said shaft and arranged to actuate said lever, means for rotating said cam on said shaft, means for operatively 100 connecting said shaft to said cam to cause the cam to rotate with the shaft, a pivoted arm arranged normally out of the path of 105 said pawl and its projection, and a connection between said shaft and said arm, whereby the rotation of said shaft will cause said arm to engage the projection of said pawl and move said pawl into an inoperative position.

110 24. In a machine of the character described, the combination, with a registering device, a ratchet wheel operatively connected therewith, a lever, and a pawl carried by 115 said lever to engage said ratchet wheel and having a projection, of a shaft, a cam rotatably mounted on said shaft and arranged to actuate said lever, means for rotating said cam on said shaft, means for operatively connecting said shaft to said cam to cause the cam to rotate with the shaft, a pivoted 120 arm arranged normally out of the path of said pawl and its projection, a connection between said shaft and said arm, whereby the rotation of said shaft will cause said arm to engage the projection of said pawl 125 and move said pawl into an inoperative position, and a retaining device to hold said arm in engagement with said projection un-

til said shaft shall have completed its rotation.

25. In a machine of the character described, the combination, with a registering device, a ratchet wheel operatively connected therewith, a lever, and a pawl carried by said lever to engage said ratchet wheel and having a projection, of a shaft, a cam rotatably mounted on said shaft and arranged 5 to actuate said lever, means for rotating said cam on said shaft, means for operatively connecting said shaft to said cam to cause the cam to rotate with the shaft, a pivoted arm arranged normally out of the path of 10 said pawl and its projection, a second arm operatively connected with the first-mentioned arm, and a part carried by said shaft and adapted to actuate said second arm when said shaft is rotated and thereby move 15 20 the first-mentioned arm into the path of the projection of said pawl.

26. In a machine of the character described, the combination, with a registering device, a ratchet wheel operatively connected therewith, a lever, and a pawl carried by 25 said lever to engage said ratchet wheel and having a projection, of a shaft, a cam rotatably mounted on said shaft and arranged to actuate said lever, means for rotating said 30 cam on said shaft, means for operatively connecting said shaft with said cam to cause the cam to rotate with the shaft, a pivoted arm arranged normally out of the path of 35 said pawl and its projection, a second arm operatively connected with the first-mentioned arm, a part carried by said shaft and adapted to actuate said second arm when 40 said shaft is rotated and thereby move the first-mentioned arm into the path of the projection of said pawl, and a locking device for retaining said first-mentioned arm in engagement with said projection and until 45 said shaft has completed its rotation.

27. In a machine of the character described, the combination, with a registering device, a ratchet wheel operatively connected therewith, a lever, and a pawl carried by 45 said lever to engage said ratchet wheel and having a projection, of a shaft, a cam rotatably mounted on said shaft and arranged to actuate said lever, means for rotating said cam on said shaft, means for operatively connecting said shaft with said cam to cause the cam to rotate with the shaft, a pivoted 50 55 arm arranged normally out of the path of said pawl and its projection, a second arm operatively connected with the first-mentioned arm, a part carried by said shaft and adapted to actuate said second arm when 60 said shaft is rotated and thereby move the first-mentioned arm into the path of the projection of said pawl, a locking device for retaining said first-mentioned arm in engagement with said projection and until 65 said shaft has completed its rotation, and

means controlled by the rotation of said cam for releasing said locking device.

28. In a machine of the character described, the combination, with a registering device, a ratchet wheel operatively connected 70 therewith, a lever, and a pawl carried by said lever to engage said ratchet wheel and having a projection, of a shaft, a cam rotatably mounted on said shaft, a driving gear rotatably mounted on said shaft, clutch 75 mechanism for connecting said gear to said cam, pawl and ratchet wheel for connecting said shaft to said cam, whereby the rotation of said shaft will rotate said cam independently of said driving gear, a pivoted arm arranged normally out of the path of said pawl and projection and having a finger, a second arm operatively connected with the first-mentioned arm, a cam disk carried by 80 said shaft and arranged to actuate said second arm to move the first arm into the path of said projection, a trip lever arranged to engage said finger and retain said first arm in its operative position, and means controlled by the movement of the lever carrying 85 the pawl for releasing said trip lever.

29. In a machine of the character described, the combination, with a registering device, a ratchet wheel operatively connected therewith, a lever, and a pawl carried by 90 said lever to engage said ratchet wheel, of a shaft, a cam rotatably mounted on said shaft and arranged to actuate said lever, a gear rotatably mounted on said shaft, clutch mechanism for connecting said 95 cam to said gear, means for rotating said gear, a one-tooth ratchet wheel rigidly secured to said shaft, a pawl connected with said cam and arranged in the path of the tooth of said one-tooth ratchet wheel, whereby the rotation of said shaft will rotate said cam independently of said gear.

30. In a machine of the character described, the combination, with a registering device, a shaft, an operating member for 110 said registering device rotatably mounted on said shaft, and means for causing said operating member to rotate with said shaft when the latter is rotated in one direction, of a flag movable from one position to another, and means controlled by the movement of said flag in one direction for rotating said shaft to cause said operating device 115 to be returned to its normal position.

31. In a machine of the character described, the combination, with a registering device, a shaft, a cam loosely mounted on said shaft and adapted to actuate said registering device, means for imparting movement to said cam relatively to said shaft, and means for causing said cam to rotate with said shaft when the latter is rotated in one direction, of a flag movable from one 120 125 position to another, and means controlled by the movement of said flag in one direction 130

for rotating said shaft to cause said cam to be returned to its initial position.

32. In a machine of the character described, the combination, with a registering device, a shaft arranged near said registering device, a lever mounted on said shaft, a pawl carried by said lever and adapted to engage said ratchet wheel, a second shaft, a cam rotatably mounted on said second shaft to actuate said lever, and means to cause said cam to rotate with said shaft, of a flag movable from one position to another, and a connection between said flag and said second shaft for moving said cam to its initial position when said flag is returned to its normal position.

33. In a machine of the character described, the combination, with a plurality of registering devices, a shaft, a plurality of cams loosely mounted on said shaft and adapted to actuate the respective registering devices, means for imparting movement to said cams relatively to said shaft, and means for causing one of said cams to rotate with said shaft, of a flag movable from one position to another, and means controlled by the movement of said flag in one direction for rotating said shaft to cause the said one of said cams to be returned to its initial position.

34. The combination, with a vehicle, a plurality of registering devices, a shaft, a plurality of cams loosely mounted on said shaft and adapted to actuate the respective registering devices, means driven from a moving part of said vehicle for operating said cams, and means for causing one of said cams to rotate with said shaft, of a flag movable from one position to another, means controlled by the movement of said flag for connecting said cams with and disconnecting the same from the moving part of said vehicle, and other means controlled by the movement of said flag for rotating said shaft to cause said one cam to be returned to its initial position.

35. In a machine of the character described, the combination, with a flag movable from one position to another, a registering device, a ratchet wheel operatively connected to said registering device, a lever, a pawl carried by said lever and adapted to engage said ratchet wheel, a shaft, a cam loosely mounted on said shaft to actuate said lever, and means for rotating said cam on said shaft, of means controlled by the movement of said flag in one direction for rotating said shaft, and a connection between said cam and said shaft, whereby the rotation of said shaft will move said cam to its zero position.

36. In a machine of the character described, the combination, with a flag movable from one position to another, a registering device, a ratchet wheel operatively con-

nected to said registering device, a lever, a pawl carried by said lever and adapted to engage said ratchet wheel, a shaft, a cam loosely mounted on said shaft to actuate said lever, and means for rotating said cam on said shaft, of a ratchet wheel rotatably mounted adjacent to said flag, an arm rigidly connected with said flag, a pawl carried by said arm and adapted to engage said ratchet wheel when said flag is returned to its normal position, a gear operatively connected to said ratchet wheel, a pinion on said shaft meshing with said gear, and a connection between said shaft and said cam, whereby, when said flag is returned to its normal position, said shaft will be returned and said cam moved to its zero position.

37. In a machine of the character described, the combination, with a registering device, a ratchet wheel operatively connected with said registering device, and a pawl to actuate said ratchet wheel, of means to check the movement of said pawl and said ratchet wheel and to move said pawl into a position to permit said ratchet wheel to move through a limited space.

38. In a machine of the character described, the combination, with a registering device, a ratchet wheel operatively connected to said registering device, and a pawl to actuate said ratchet wheel, a portion of said pawl having a forwardly and upwardly inclined lower surface, a stop arranged to engage said pawl and having a beveled edge to engage the inclined surface thereof.

39. In a machine of the character described, the combination, with a registering device, a ratchet wheel operatively connected to said registering device, and a pawl to actuate said ratchet wheel, of a stop arranged to check the movement of said pawl and move the same partially out of engagement with said ratchet wheel, thereby retaining the pawl in the path of the following tooth on said ratchet wheel and also permitting said ratchet wheel to be adjusted to align said registering device.

40. In a machine of the character described, the combination, with a registering device, a ratchet wheel operatively connected therewith, and a pawl arranged to actuate said ratchet wheel, said pawl having a recess in its forward edge provided with an inclined upper wall, of a beveled stop adapted to enter said recess and engage the inclined wall thereof, thereby checking the movement of said pawl, retaining the same in the path of the following tooth on the ratchet wheel to check the movement of the ratchet wheel and lifting the pawl out of engagement with the base of said tooth to permit the ratchet wheel to be adjusted.

41. In a machine of the character described, the combination, with a registering device, a ratchet wheel operatively connect-

ed with said registering device, and a pawl for actuating said ratchet wheel, of means for printing a record from said registering device, and means independent of said pawl 5 to engage said ratchet wheel and move said registering device into printing position.

42. In a machine of the character described, the combination, with a registering device, an actuator therefor comprising a 10 gear, a driving gear to operate said actuator gear, a ratchet wheel operatively connected with said driving gear, and a pawl for actuating said ratchet wheel, of printing mechanism for taking a record from said 15 registering device, and means controlled by the operation of said printing mechanism for moving said registering device into printing alinement.

43. In a machine of the character described, the combination, with a registering device, a ratchet wheel operatively connected with said registering device, and a pawl for actuating said ratchet wheel, of printing mechanism to take a record from said 25 registering device, and an alining pawl operatively connected with said printing mechanism and adapted to engage said ratchet wheel to move said registering device into printing alinement.

44. In a machine of the character described, the combination, with a signal movable from one position to another, registering devices, and driving mechanism for said registering devices comprising a plurality 35 of gears, one of which is moved into and out of mesh with another thereof, of means actuated by the movement of said signal to move said movable gear into and out of mesh with said other gear.

45. In a machine of the character described, the combination, with a signal movable from one position to another, a registering device, an actuating gear for said registering device, a pair of pinions, one of 45 which is connected with said actuating gear, and means for rotating the other of said pinions, of a connecting gear adapted to mesh with both of said pinions, and means controlled by the movement of said signal 50 for moving said connecting gear into and out of mesh with said pinions.

46. In a machine of the character described, the combination, with a registering device, driving mechanism therefor, and a 55 connecting member for operatively connecting said driving mechanism with said registering device, of a flag comprising a pivoted lever, a cam operatively connected to said lever, and means actuated by the movement of said cam for moving said connecting member into and out of its operative position.

47. In a machine of the character described, the combination, with a registering 65 device, a gear operatively connected there-

with, a pair of pinions, one of which is positively driven and the other of which meshes with said gear, and a connecting gear adapted to be moved into and out of mesh with said pair of pinions, of a flag comprising a 70 lever, a cam operatively connected to said lever, and mechanism for connecting said cam with said connecting gear, whereby the movement of said flag will control the movement of said gear.

48. In a machine of the character described, the combination, with a registering device, a gear connected with said registering device, a pair of pinions, one of which meshes with said gear, means for positively 80 rotating the other of said pinions, and a connecting gear adapted to be moved into and out of mesh with said pair of pinions, of a shaft, a sleeve rotatably mounted on said shaft, a flag comprising a lever rigidly 85 connected with said sleeve, an arm rigidly secured to said sleeve, a second shaft, a slotted arm rigidly secured to said second shaft, a pin carried by the first arm and adapted to enter the slot of the second arm 90 to rotate said shaft when said flag is moved from one position to the other, a cam connected to the other end of said shaft, and mechanism actuated by the movement of said cam for moving said connecting gear 95 into and out of mesh with said pair of pinions.

49. The combination, with a vehicle, clock mechanism and a plurality of registering devices, of means controlled by the movement 100 of said vehicle for operating one of said registering devices, means controlled by said clock mechanism for operating another of said registering devices, and means adapted to be controlled either by the movement of 105 said vehicle or by said clock mechanism for actuating another of said registering devices, and means for printing a record from said registering devices.

50. The combination, with a vehicle and 110 clock mechanism, of two series of registering devices, each series containing a fare registering device, means adapted to be controlled either by the movement of said vehicle or by said clock mechanism for actuating 115 said fare registering devices, and means for printing an independent record from each series of said registering devices.

51. The combination, with a vehicle, a fare registering device, mechanism controlled by the movement of said vehicle to operate said registering device, and a ratchet wheel connected with said operating mechanism, of a lever, a flag movable from one position to another, a pawl carried by said lever and held normally out of engagement with said ratchet wheel, a projection carried by said pawl, a fixed guide arranged in the path of said projection and adapted to be engaged by the same 125 130

when said flag is moved into one of its positions to move said pawl into engagement with said ratchet wheel.

52. The combination, with a vehicle, a fare registering device, mechanism controlled by the movement of said vehicle to operate said registering device, and a ratchet wheel connected with said operating mechanism, of a lever a flag movable from one position to another, a pawl carried by said lever and held normally out of engagement with said ratchet wheel, a lateral projection carried by said pawl, a fixed cam arranged in the path of said projection, adapted to 10 be engaged by the projection to move said pawl into engagement with said ratchet wheel when said flag is moved into one of its positions and adapted to engage said projection to move said pawl out of engagement with said ratchet wheel when said flag is moved into another position.

53. In a machine of the character described, the combination, with a flag movable from one position to another, a fare registering device, means for actuating said fare registering device and a ratchet wheel connected with said fare registering device, of a lever movable about an axis substantially coincident with the axis of said ratchet 25 wheel and operatively connected with said flag, a pawl carried by said lever and adapted to actuate said ratchet wheel when said lever is advanced.

54. In a machine of the character described, the combination, with a fare registering device, means for actuating the same, a ratchet wheel connected with said fare registering device, a lever, a pawl carried by said lever and held normally out of engagement with said ratchet wheel, and means for causing said pawl to engage said ratchet wheel when said lever is advanced, of a gear connected to said lever, and a flag movable from one position to another and 40 operatively connected with said gear, whereby the movement of said flag in one direction will actuate said ratchet wheel.

55. In a machine of the character described, the combination, with a registering 50 device actuating mechanism therefor, and a ratchet wheel operatively connected with said registering device, of a lever, a pawl carried by said lever and adapted to engage said ratchet wheel to advance said registering device when said lever is moved in one direction, means for holding said pawl out of engagement with said ratchet wheel when said lever is moved in the opposite direction, and a friction member 55 tending to move said ratchet wheel rearwardly when said lever is returned to its starting point.

56. In a machine of the character described, the combination, with a registering 60 device, actuating mechanism therefor,

and a ratchet wheel operatively connected with said registering device and having a laterally extending flange, of a lever, a pawl carried by said lever and adapted to engage said ratchet wheel when said lever is moved in one direction, means for holding said pawl out of engagement with said ratchet wheel when said lever is moved in the opposite direction, and a friction member carried by said lever and adapted to engage 75 said flange when said lever is moved in said opposite direction.

57. In a machine of the character described, the combination, with a registering device, actuating mechanism therefor, and 80 a ratchet wheel operatively connected with said registering device and having a laterally extending flange, of a lever, a pawl carried by said lever and held normally out of engagement with said ratchet wheel, a 85 laterally extending projection carried by said pawl, a fixed flange arranged in the path of said projection and adapted to be engaged thereby to move said pawl into engagement with said ratchet wheel when said 90 lever is advanced and to be engaged by said projection to hold said pawl out of engagement with said ratchet wheel when said lever is returned to its starting point, a friction pawl carried by said lever, and a 95 friction connection between the first-mentioned pawl and said friction pawl, whereby, when said first-mentioned pawl is held out of engagement with said ratchet wheel by said cam, said friction pawl will engage 100 said flange.

58. In a machine of the character described, the combination, with a registering device, actuating mechanism therefor comprising an operating member, a pawl connected with said operating member, a one-tooth ratchet wheel connected with said registering device, and a ratchet wheel interposed between said one-tooth ratchet wheel and said registering device, of a lever, a 105 pawl carried by said lever and adapted to engage said ratchet wheel when said lever is moved forward to advance said registering device, thereby causing said one-tooth ratchet wheel to run ahead of its pawl, a 110 friction member carried by said lever and adapted to engage the part carried by said ratchet wheel when said lever is returned to its starting point, thereby moving said one-tooth ratchet wheel into engagement 115 with its pawl.

59. The combination, with a vehicle comprising ground wheels and a registering device, of a worm operatively connected to one of the ground wheels of said vehicle and 120 adapted to be rotated thereby, a worm wheel meshing with said worm, a pair of pinions having their axes substantially coincident, one of said pinions being positively rotated by said worm wheel, a gear meshing with 125 130

the other of said pinions, means for connecting said pinions to cause the same to rotate in unison, and means for operatively connecting said gear with said registering device.

60. The combination, with a vehicle comprising ground wheels, a registering device, and a worn operatively connected with one of the ground wheels of said vehicle, of a shaft, a worm wheel rotatably mounted on said shaft and meshing with said worm, a gear rotatably mounted on said shaft, clutch mechanism for connecting said gear to said worm wheel, a second shaft, a pinion fixed on said second shaft, a second pinion fixed on said shaft, a third pinion rotatably mounted on said shaft, a gear mounted on the first-mentioned shaft and meshing with said third pinion, means for connecting the two last-mentioned pinions to cause them to rotate in unison, and means for connecting said gear with said registering device.

61. The combination with a vehicle, a resetting shaft, a group of counters mounted thereon, and means for actuating said counters from a moving part of said vehicle of a shaft, a flag movably mounted on said shaft and adapted to be supported in a plurality of positions, a gear rotatably mounted on said shaft, a gear on said resetting shaft meshing with the first-mentioned gear, and an operative connection between said flag and said first-mentioned gear, whereby the movement of said flag into one of its positions will reset said counters to zero.

62. The combination, with a vehicle, a resetting shaft, a group of counters mounted on said resetting shaft, and means for actuating said counters from a moving part of said vehicle, of a stud shaft, a flag movably mounted on said stud shaft and adapted to be supported in a plurality of positions, a ratchet wheel mounted on said stud shaft, a gear rigidly secured to said ratchet wheel and operatively connected with said resetting shaft, an arm rigidly secured to said flag, and a pawl carried by said arm and adapted to engage said ratchet wheel to rotate said gear and said resetting shaft, whereby the movement of said flag into one of its positions will reset said counters to zero.

63. The combination, with a vehicle, a resetting shaft, a group of counters mounted thereon, and means for actuating said counters from a moving part of said vehicle, of a stud shaft, a flag rotatably mounted on said stud shaft and adapted to be supported in a plurality of positions, a ratchet wheel mounted on said stud shaft, a gear rigidly secured to said ratchet wheel and operatively connected with said resetting shaft, an arm rigidly secured to said flag, a pawl carried by said arm and adapted to engage said ratchet wheel to rotate said gear and

said resetting shaft, said pawl having an inclined outer edge, a stop arranged in the path of said inclined edge and serving to check the movement of said pawl and to force the same into engagement with said ratchet wheel to check the movement of said ratchet wheel.

64. In a machine of the character described, the combination, with a registering device, a shaft to control the operation of said registering device, a flag rigidly secured to said shaft and serving as an operating handle therefor, an arm rigidly secured to said shaft, and a spring-pressed pawl held normally in the path of said arm, of printing mechanism for taking a record from said registering device, an operating shaft for said printing mechanism, a handle mounted on said shaft for actuating the same, a plate rigidly secured to said shaft, a pitman pivotally connected at one end to said plate and having a slidable connection at the other end with said pawl, whereby the manipulation of said handle to operate said printing mechanism will move said pawl out of the path of the arm on the first-mentioned shaft.

65. In a machine of the character described, the combination, with a registering device, a flag movable from one position to another and controlling the operation of said registering device, a locking member connected with said flag, and a second locking member co-operating with the first-mentioned locking member to retain said flag against movement, of printing mechanism to take a record from said registering device, an operating device for said printing mechanism, means controlled by said operating device for moving said second locking member into inoperative position, and means for retaining said second locking member in said inoperative position until said flag has completed its movement.

66. In a machine of the character described, the combination, with a registering device, a flag movable from one position to another and controlling the operation of said registering device, a locking member connected with said flag, and a second locking member co-operating with the first-mentioned locking member to retain said flag against movement, of printing mechanism to take a record from said registering device, an operating device for said printing mechanism, means controlled by said operating device for moving said second locking member into inoperative position, means for retaining said second locking member in said inoperative position until said flag has completed its movement, and means controlled by the movement of said flag for releasing said second locking member from said retaining device.

67. In a machine of the character de-

scribed, the combination, with a registering device, a flag movable from one position to another and controlling the operation of said registering device, an arm rigidly connected with said flag, and a pawl adapted to extend into the path of said arm when said flag is in either of its positions, of printing mechanism, an operating device for said printing mechanism, means controlled by the movement of said operating device for moving said pawl out of the path of said arm, a detent to retain said pawl in its inoperative position until said flag has been moved from one position to another, and means actuated by the movement of said flag for releasing said pawl from said detent.

68. In a machine of the character described, the combination, with a registering device, a flag movable from one position to another and controlling the operation of said registering device, an arm rigidly connected with said flag, and a pawl adapted to extend into the path of said arm when said flag is in either of its positions, of printing mechanism, an operating device for said printing mechanism, means controlled by the movement of said operating device for moving said pawl out of the path of said arm, a detent to retain said pawl in its inoperative position until said flag has been moved from one position to another, a finger operatively connected with said detent, and a projection carried by said arm and adapted to engage said finger to disconnect said detent from said pawl.

69. In a machine of the character described, the combination, with a registering device, a flag movable from one position to another and controlling the operation of said registering device, an arm rigidly connected with said flag, a pawl, a spring tending to move said pawl into the path of said arm when said flag is in either of its positions, an arm rigidly secured to said pawl and having a lateral projection, a detent adapted to extend above or below said projection when said pawl is in its operative position, and a spring for moving said detent into the path of said projection when said pawl is moved into its inoperative position, a finger rigidly connected with said detent, and a pin carried by said arm and adapted to engage said finger to move said detent out of the path of said projection when said flag is moved from one position to another, of printing mechanism for taking a record from said registering device, and means controlled by the operation of said printing mechanism for moving said pawl into its inoperative position.

70. In a machine of the character described, the combination, with a registering device, a flag movable from one position to another and controlling the operation of said reg-

istering device, a locking member rigidly connected with said flag, and a pawl adapted to extend into the path of said locking member, of printing mechanism for taking a record from said registering device, an operating handle for said printing mechanism, a connection between said operating handle and said pawl to move said pawl out of the path of said locking member when said operating handle has been moved, and means for locking said flag against movement until said operating handle has been returned to its normal position.

71. In a machine of the character described, the combination, with a registering device, a flag movable from one position to another and controlling the operation of said registering device, a locking member rigidly connected with said flag, and a pawl adapted to extend into the path of said locking member, of printing mechanism for taking a record from said registering device, an operating handle for said printing mechanism, a connection between said operating handle and said pawl to move said pawl out of the path of said locking member when said operating handle has been moved, and notched disks carried by said handle and said flag, respectively, and coöperating to prevent the movement of either said handle or said flag until the other of said parts is in its normal position.

72. In a machine of the character described, the combination, with a registering device, a flag movable from one position to another and controlling the operation of said registering device, printing mechanism for taking a record from said registering device, and an operating handle for said printing mechanism, of notched disks rigidly connected with said flag and said operating handle, respectively, and coöperating to lock either of said members against movement, when the other is out of its normal position.

73. In a machine of the character described, the combination, with a registering device, and a flag movable from one position to another and controlling said registering device, of a locking member connected to said flag, and a coöperating locking member adapted to engage the first-mentioned locking member when said flag is in either of its positions, and means controlled by the normal operation of said machine to disengage said locking members.

74. In a machine of the character described, the combination, with a registering device, and a flag movable from one position to another and controlling said registering device, of a locking member connected to said flag, a coöperating locking member adapted to engage the first-mentioned locking member when said flag is in either of its positions, means controlled by the normal

operation of said machine to disengage locking members, and an arrester to cause one movement of said flag to be completed before it can be moved in the opposite direction.

75. In a machine of the character described, the combination, with a registering device, and a printing mechanism for taking a record from said registering device comprising a reciprocatory carriage, and a device for actuating said carriage, of an operating handle, a cam connected to said handle, and an operative connection between said cam and the actuating device for said carriage.

76. In a machine of the character described, the combination, with a registering device, printing mechanism for taking a record from said registering device and comprising a shaft, and a pinion on said shaft, of a segment meshing with said pinion, a cam, means for rotating said cam, and means for connecting said cam with said segment.

77. In a machine of the character described, the combination, with a registering device, printing mechanism for taking a record from said registering device and comprising a shaft, a pinion on said shaft, a reciprocatory carriage operatively connected with said shaft, and a platen mounted on said carriage, of a second shaft, a plate rotatably mounted on said second shaft and having a cam groove therein, means for rotating said plate, a pitman having a pin extending into said groove, and a toothed segment connected with said pitman and meshing with said pinion.

78. In a machine of the character described, the combination, with a registering device, printing mechanism for taking a record from said registering device and comprising a shaft, and a pinion on said shaft, of a second shaft, a cam plate rotatably mounted on said second shaft, a ratchet wheel rigidly secured to said cam, a handle rotatably mounted on said shaft, a plate rigidly connected to said handle, a pawl carried by said plate and arranged to mesh with said ratchet wheel, a toothed segment meshing with said pinion, and a pitman connecting said cam plate with said segment.

79. In a machine of the character described, the combination, with a registering device, and printing mechanism for taking a record from said registering device, of a ratchet wheel operatively connected with said printing mechanism, a plate, a pawl carried by said plate, arranged to engage said ratchet wheel and having a heel portion, means for rotating said plate, and a fixed stop arranged to be engaged by the heel portion of said pawl and to move the same toward said ratchet wheel, thereby

checking the movement of both the pawl and ratchet wheel.

80. In a machine of the character described, the combination, with a registering device, and a printing mechanism for taking a record from said registering device and comprising a shaft and a pinion, of a cam plate having two grooves therein, a toothed segment meshing with said pinion, a pitman connected at one end of said segment and having a pin adapted to enter the grooves in said cam plate, said grooves being so arranged that the rotation of said cam will cause said pin to travel in one of said grooves, and means for rotating the shaft of said printing mechanism independently of said cam and causing said pin to enter the second of said grooves.

81. In a machine of the character described, the combination, with a group of printing counters, a ratchet wheel operatively connected with said printing counters, means for actuating said ratchet wheel, and an alining pawl adapted to operate said ratchet wheel to move said printing counters into printing alinement, of printing mechanism comprising a shaft, a plate rigidly secured to said shaft and having a recess in the edge thereof, a lever having a projection arranged to rest in said recess when said printing mechanism is in its normal position, a connection between said lever and said alining pawl, whereby, when the shaft of said printing mechanism is rotated, said projection will be forced out of said recess and said alining pawl moved into operative engagement with said ratchet wheel.

82. In a machine of the character described, the combination, with two sets of registering devices, means for simultaneously printing a record from each of said registering devices, of an actuating device controlled by the operation of said printing mechanism for feeding the paper to both sets of said registering devices.

83. In a machine of the character described, the combination, with two sets of registering devices, and means for simultaneously printing a record from each set of said registering devices, of separate mechanism for feeding the paper to each set of said registering devices, the feeding mechanism for one set of said registering devices feeding the paper a greater distance than the feeding mechanism for the other set of said registering devices feeds the paper, and a single actuating device for both feeding mechanisms.

84. In a machine of the character described, the combination, with two sets of registering devices, printing mechanism for taking a record therefrom, and separate mechanisms for feeding the paper to said registering devices, each comprising a set of feeding rollers, a cam controlled by the

operation of said printing mechanism, and connections between said cam and both sets of said feeding rollers.

85. In a machine of the character described, the combination, with a registering device, and printing mechanism for taking a record therefrom, of mechanism for feeding the paper to said registering device comprising feeding rollers, a ratchet wheel connected to one of said rollers, an arm loosely mounted on the shaft of said roller and having a pawl arranged to engage said ratchet, a cam controlled by the operation of said printing mechanism, and means for operatively connecting said cam to the arm carrying said pawl.

86. In a machine of the character described, the combination, with a registering device, and printing mechanism for taking a record therefrom, of a pair of coöperating feeding rollers, intermeshing gears carried by said rollers, a ratchet wheel rigidly secured to one of said rollers, an arm loosely mounted on the shaft of said roller, a pawl carried by said arm, an operating handle for said printing mechanism, a cam operatively connected with said operating handle, and a pitman connecting said cam with the arm carrying said pawl.

87. In a machine of the character described, the combination, with two sets of registering devices, and mechanism for simultaneously printing a record from each set of said registering devices, of a pair of feeding rollers for each of said registering devices, two cam plates controlled by the operation of said printing mechanism and having cam grooves of different contour, and means for connecting one of said cam plates with each pair of said feeding rollers, whereby, the operation of said printing mechanism will cause a different movement to be imparted to each pair of said rollers.

88. In a machine of the character described, the combination, with a registering device, and mechanism for printing a record from said registering device, of a pair of feeding rollers, means controlled by the operation of said printing mechanism for actuating said feeding rollers, and an electrotype plate secured to one of said rollers and forming a part of the feeding surface thereof.

89. In a machine of the character described, the combination, with a registering device, and mechanism for printing a record from said registering device, of a pair of feeding rollers, a cam operatively connected with said feeding rollers, said cam being of such a construction as to impart two movements to said feeding rollers for each rotation of said cam, the combined length of said movement being equal to the circumference of one of said rollers, and an electrotype plate secured to and forming

part of the feeding surface of one of said rollers.

90. The combination, with a vehicle, a registering device, means actuated from a moving part of said vehicle for operating said registering device, mechanism for printing a record from said registering device, a flag movable from one position to another and controlled by the operation of said registering device, and an operating device for said printing mechanism, of a paper feeding device arranged to feed the paper to said registering device, means controlled by the movement of said operating device for actuating said feeding mechanism, paper cutting mechanism arranged beyond said feeding mechanism, and means also controlled by the operation of said operating device for said printing mechanism for actuating said paper cutting device.

91. The combination, with a vehicle, a registering device, means actuated from a moving part of said vehicle for operating said registering device, mechanism for printing a record from said registering device, a flag movable from one position to another and controlled by the operation of said registering device, and an operating device for said printing mechanism, of paper feeding rollers, means controlled by the operation of said operating device for actuating said rollers, a paper cutter arranged beyond said feeding rollers, and a cam plate also controlled by the operation of said operating device for said printing mechanism and operatively connected with said paper cutter.

92. The combination, with a vehicle, a registering device, means actuated from a moving part of said vehicle for operating said registering device, mechanism for printing a record from said registering device, a flag movable from one position to another and controlled by the operation of said registering device, an operating device for said printing mechanism, and paper feeding mechanism, of a paper cutter comprising a fixed member having a spring-pressed cutter bar and a movable member having a cutting edge of less length than said cutter bar, projections carried by said movable member and adapted to engage said cutter bar, and means controlled by said operating device for said printing mechanism for actuating said movable member.

93. The combination, with a vehicle, a registering device, means actuated from a moving part of said vehicle for operating said registering device, mechanism for printing a record from said registering device, a flag movable from one position to another and controlled by the operation of said registering device, an operating device for said printing mechanism, and paper feeding

- mechanism, of cutting mechanism comprising a fixed member, a cutter bar slidably mounted therein, springs tending to move said cutter bar outward, a movable member 5 having an elongated recess, the base of which constitutes a cutting edge, those portions of said member at the end of said recess being arranged to engage the cutter bar and the movement of the cutter bar being such 10 that it is never moved out of engagement with the cutter bar, and means controlled by said operating device for said printing mechanism for actuating said movable member.
- 15 94. The combination, with a vehicle, a registering device, means actuated from a moving part of said vehicle for operating said registering device, mechanism for printing a record from said registering device, a 20 flag movable from one position to another and controlled by the operation of said registering device, an operating device for said printing mechanism, paper feeding mechanism, and a paper cutter, of a series of 25 cams, means for operatively connecting said cams with said printing mechanism, said feeding mechanism and said paper cutter, respectively, and a single actuating device for imparting movement to said cams.
- 30 95. In a machine of the character described, the combination, with a registering device, printing mechanism for printing a record from said registering device, paper feeding mechanism, and a paper cutter, of 35 a shaft, a sleeve rotatably mounted on said shaft, means for rotating said sleeve, a plurality of plates rigidly secured to said sleeve, and a plurality of grooves formed in said plates, a corresponding plurality of pitmen 40 operatively connected with said printing mechanism, said feeding mechanism and said cutter, respectively, and each having a pin adapted to enter one of said cam grooves, whereby the rotation of said sleeve will operate said parts in a prearranged order.
- 45 96. The combination, with a vehicle having a driver's station and a passenger compartment, of a registering device arranged to be visible from said driver's station and 50 from said passenger compartment, means to print a record from said registering device, and means to deliver said record to said passenger compartment.
- 55 97. The combination, with a vehicle having a driver's station and a passenger compartment, of a registering device arranged to be visible from said driver's station and from said passenger compartment, means to print a record from said registering device, 60 and means to sever said record and deliver the same to said passenger compartment.
98. The combination, with a vehicle having a driver's station and a passenger compartment, of a registering device arranged 65 to be visible from said driver's station and
- from said passenger compartment, means to print a record from said registering device, 70 means to sever said record, and a conveyer adapted to receive said record and deliver the same to said passenger compartment. 70
99. In a machine of the character described, the combination, with a main frame, a mileage registering device and a fare registering device arranged within said main frame, two shafts mounted on said 75 main frame, a drive wheel rotatably mounted on one of said shafts, and a plurality of driving gears rotatably mounted on the other of said shafts and operatively connected with the respective registering devices, of a cam mounted on the first-mentioned shaft, operatively connected with said drive wheel and adapted to actuate the driving gear for said mileage registering device, a pawl connected with said cam, a one-tooth ratchet wheel mounted on said shaft and adapted to engage said pawl when said shaft is rotated, a gear on said second shaft adapted to actuate the driving gear for the fare registering device, a pawl 80 connected with said gear, and a one-tooth ratchet wheel rigidly secured to said second shaft between said gear and said driving gear, and means for simultaneously actuating said shafts to cause said one-tooth 85 ratchet wheels to engage their pawls and move the respective parts to their normal positions. 90
100. In a machine of the character described, the combination, with a main frame, 100 a mileage registering device and a fare registering device arranged within said main frame, two shafts mounted on said main frame, a drive wheel rotatably mounted on one of said shafts, and a plurality of driving gears rotatably mounted on the other of said shafts and operatively connected with the respective registering devices, of a cam mounted on the first-mentioned shaft, 105 operatively connected with said drive wheel and adapted to actuate the driving gear for said mileage registering device, a pawl connected with said cam, a one-tooth ratchet wheel mounted on said shaft and adapted to engage said pawl when said shaft is rotated, a gear on said second shaft adapted to actuate the driving gear for the fare registering device, a pawl connected with said gear, and a one-tooth ratchet wheel 110 rigidly secured to said second shaft between said gear and said driving gear, a signal, and means controlled by said signal for resetting said registering devices to zero and rotating both of said shafts to cause said ratchet wheels to engage their respective 115 pawls, thereby returning the respective parts to their normal positions. 120
101. In a machine of the character described, the combination, with a counter shaft, a counter comprising a counter disk, 125

and a gear connected thereto, and an actuator for said counter comprising a gear, of a fine tooth gear rotatably mounted on said counter shaft and meshing with the actuator gear, a transfer shaft, a fine tooth gear mounted on said transfer shaft and meshing with the fine tooth gear on said counter shaft, a coarse tooth gear loosely mounted on said counter shaft, rigidly connected with said fine tooth gear and meshing with the gear of said counter.

102. In a machine of the character described, the combination, with a counter shaft, a counter comprising a counter disk and a gear connected thereto, and an actuator for said counter comprising a gear, of a fine tooth gear rotatably mounted on said counter shaft and meshing with the actuator gear, a transfer shaft, a fine tooth gear mounted on said transfer shaft and meshing with the fine tooth gear on the counter shaft, a coarse tooth gear loosely mounted on said counter shaft, rigidly connected with said fine tooth gear and meshing with the gear of said counter, means for moving said counter shaft to disengage said fine tooth gears, and means for resetting said counter to zero.

103. In a machine of the character described, the combination, with a rotatable resetting shaft, a counter mounted thereon comprising a counter disk and a gear connected thereto, and an actuator comprising a gear, of a fine tooth gear rotatably mounted on said resetting shaft and meshing with said actuator gear, a swinging transfer shaft, a fine tooth gear mounted on said transfer shaft and meshing with the fine tooth gear on the resetting shaft, a coarse tooth gear mounted on said transfer shaft, rigidly connected with said fine tooth gear and meshing with the gear of said counter, and means controlled by the rotation of said resetting shaft for moving said swinging transfer shaft.

104. In a machine of the character described, the combination, with a rotatable resetting shaft, a counter mounted thereon comprising a counter disk and a gear connected thereto, and an actuator comprising a gear, of a fine tooth gear rotatably mounted on said resetting shaft, and meshing with said actuator gear, a swinging transfer shaft, a fine tooth gear mounted on said transfer shaft and meshing with the fine tooth gear on the resetting shaft, a coarse tooth gear mounted on said transfer shaft, rigidly connected with said fine tooth gear and meshing with the gear of said counter, a collar rigidly secured to said resetting shaft and having a notch therein, and a projection connected with said swinging transfer shaft and normally resting within the notch of said collar, whereby the rotation of said shaft and said collar will force said pro-

jection out of said notch and move said swinging transfer shaft.

105. In a machine of the character described, the combination, with three series of registering devices, each series including a trip number registering device, of a single actuator for simultaneously actuating each of said trip number registering devices prior to the beginning of each trip.

106. In a machine of the character described, the combination, with a trip resetting shaft, and a total resetting shaft, two series of registering devices on said trip resetting shaft, and a series of registering devices on the total resetting shaft, each series of registering devices including a trip number registering device, of an actuator carried by said trip resetting shaft to simultaneously actuate each of said trip number registering devices each time said trip resetting shaft is reset to zero.

107. In a machine of the character described, the combination, with a trip resetting shaft and a total resetting shaft, two trip number registering devices carried by said trip resetting shaft and a trip number registering device carried by said total resetting shaft, each of said trip number registering devices comprising a counter disk and a gear connected thereto, of a pinion arranged to mesh simultaneously with the gears of one of the trip number registering devices for the trip resetting shaft and the registering device for the total resetting shaft, a train of gearing connecting the gear for the total trip number registering device with the second trip number registering device on the trip resetting shaft, and a one-tooth gear carried by said trip resetting shaft and adapted to actuate said pinion each time said trip resetting shaft is rotated.

108. In a machine of the character described, the combination, with a resetting shaft, two registering devices carried thereby, and actuating gears for said registering devices, of a shaft, gears carried by said shaft and meshing with the actuating gears for said registering devices, a ratchet wheel rigidly secured to said shaft, a push rod extending transversely to said shaft, and a pawl carried by said push rod and adapted to rotate said shaft to actuate said registering devices.

109. In a machine of the character described, the combination, with two resetting shafts, and an actuator shaft arranged in a vertical plane between the vertical planes of said resetting shafts, of two registering devices carried by one of said resetting shafts, a registering device carried by the other of said resetting shafts, actuator gears mounted on said actuator shaft and operatively connected with said registering devices, a ratchet wheel rigidly secured to said actu-

- ator shaft, and a pawl carried by said push bar and adapted to engage said ratchet wheel to rotate said actuator shaft and actuate said registering devices.
- 5 110. The combination, with a vehicle, clock mechanism having a dial arranged to indicate the time, and printing counters, of means controlled by the movement of said vehicle for operating one of said printing 70 counters, means controlled by the clock mechanism for operating another of said printing counters, means adapted to be controlled either by the movement of said vehicle or said clock mechanism for actuating 10 a third set of printing counters, and means for printing a record from said printing counters.
- 15 111. The combination, with a vehicle, and a clock mechanism having a dial arranged to indicate the time, of two series of printing 20 counters, each series containing a fare counter, means adapted to be controlled either by the movement of said vehicle or by said clock mechanism for actuating said fare 25 counters, and means for printing an independent record from each series of said printing counters.
- 20 112. The combination, with a vehicle, and a clock mechanism having a dial arranged to indicate the time, of two series of printing 30 counters, each series containing a fare counter, means adapted to be controlled either by the movement of said vehicle or by said clock mechanism for actuating said fare 35 counters, means for advancing said fare counters independently of the other counters, and means for printing a record from each series of said counters.
- 30 113. In a machine of the character de- 40 scribed, the combination, with a registering device, a shaft, an operating member rotatably mounted on said shaft and operatively connected with said registering device, means for imparting movement to said operating member relatively to said shaft, means for causing said operating member to rotate with said shaft, and a pinion connected with said shaft, of a flag movable from one position to another, a gear meshing with 45 said pinion, and a connection between said flag and said gear to cause the latter to be actuated when said flag is moved in one direction, whereby said shaft is rotated and said actuating member returned to its initial 50 position.
- 45 114. In a machine of the character de- 55 scribed, the combination, with a resetting shaft, counters mounted thereon, a pinion connected with said resetting shaft, a second shaft, an operating member rotatably mounted on said second shaft and operatively connected with said counters, means for imparting movement to said operating member relatively to said shaft, means for 60 causing said operating member to rotate with said shaft, and a pinion connected with said second shaft, of a flag movable from one position to another, a gear meshing with both of said pinions, and a connection between said flag and said gear to cause the latter to be actuated when the flag is moved in one direction, whereby said counters are reset to zero and said operating member is returned to its initial position.
- 55 115. In a machine of the character de- 65 scribed, the combination, with a resetting shaft, counters mounted thereon, a pinion secured to said resetting shaft, a second shaft, a cam rotatably mounted on said second shaft and arranged to actuate said counters, means for rotating said cam relatively to said shaft, means for connecting said cam and said shaft to cause the cam to rotate with the shaft, and a pinion carried by said shaft, of a flag movable from one position to another, a gear meshing with both said pinions, and a clutch connection between said flag and said gear to cause the latter to be actuated when the flag is moved in one direction, whereby said counters are reset to 70 zero and said cam returned to its initial position.
- 60 116. In a machine of the character de- 75 scribed, the combination, with a registering device, means to support ticket-forming material within said machine, and means for printing upon each operation thereof, a single record from said registering device on said ticket-forming material, of means for preventing the removal of said ticket- 80 forming material until two successive records from said registering device have been printed thereon.
- 65 117. In a machine of the character de- 85 scribed, the combination, with a registering device, means to support ticket-forming material within said machine, and means for printing two different records from said registering device on said ticket-forming material, of means for feeding from the machine that portion of said ticket-forming material containing said two records.
- 70 118. In a machine of the character de- 90 scribed, the combination, with a registering device, means to support ticket-forming material within said machine, and means for printing two different records from said registering device on said ticket-forming material, of means for severing and discharging that portion of said ticket-forming material containing said two records.
- 75 119. In a machine of the character de- 100 scribed, the combination, with a registering device, operating mechanism therefor, means for connecting said registering device with said operating mechanism and disconnecting the same therefrom, means to support ticket-forming material within said machine, and devices for printing a record from said registering device on said ticket- 105 forming material.

forming material, of means for causing two different records from said registering device to be printed on said ticket-forming material before the ticket can be removed 5 from the machine.

120. The combination, with two sets of trip registering devices, each set including devices to register the same item, and means for actuating said registering devices, of 10 printing mechanism comprising an actuating member, means to print a record from each of said trip registering devices upon each operation of said actuating member and separate paper feeding devices for the 15 respective registering devices, said feeding devices being operatively connected with said printing mechanism.

121. The combination, with two sets of trip registering devices, each set including 20 devices to register the same item, of an actuating device for each of said trip registering devices, means to take a record from each of said trip registering devices and separate devices to feed webs of paper past the 25 respective registering devices.

122. In a machine of the character described, the combination, with a registering device, and printing mechanism for taking a record therefrom, of a device for feeding 30 paper to said registering device, and means for causing said feeding device to advance the paper different distances on alternate operations thereof.

123. In a machine of the character described, the combination, with a registering device, and printing mechanism for taking a record therefrom, of a device controlled 35 by the operation of said printing mechanism for feeding paper to said registering device, and means for causing said feeding device to advance the paper different distances on alternate operations of said printing mechanism.

124. In a taximeter, a registering mechanism, means for holding a tape in close relation to the registering mechanism, an actuator movable from an initial point through a cycle of positions to its starting point, and means operative during such 45 movement to cause two impressions to be printed upon the tape to indicate different data, and means operating in conjunction therewith for advancing the tape a slight 50

distance between the two printing operations.

125. A taximeter comprising a registering mechanism, means for holding a tape in printing position, mechanism for first operating the printing mechanism to print the data on the registering mechanism upon the 55 tapes, then to advance the tapes a slight distance, and thereafter to operate the printing mechanism a second time to print different data, and additional means for removing the printed section of the tapes from printing position after the second printing operation.

126. A taximeter comprising a registering mechanism, a printing mechanism, tape feeding mechanism and a handle movable 70 from an initial point through a cycle of positions to its starting point, means operated during such movement for printing the initial data on the registering wheels upon the tapes, for advancing the tapes a slight 75 distance, for printing the final data on the registering wheels on the tapes and for removing the printed section of the tapes from printing position.

127. In a machine of the character described, the combination, with a registering device, means to support ticket-forming material adjacent to said registering device, and means for printing two different records 80 from said registering device on said ticket-forming material, of means to advance said material a short distance after the first of said records has been printed, and a longer distance after the second of said records has 85 been printed.

128. In a machine of the character described, the combination, with a registering device, and a support for ticket-forming material, of means for printing a record from 90 said registering device, advancing the material a short distance, printing a second record from said registering device and feeding that portion of the material containing the two records from the machine.

In testimony whereof, we affix our signatures in presence of two witnesses.

WILFRED I. OHMER.
JOHN E. McALLISTER.
